[57] ABSTRACT

A sealing assembly for providing a sliding seal between two members, such as the housing and rotor of a rotary engine. A groove is formed in one member and extends substantially transversely of the direction of movement of that member relative to the other member. The seal blade is received in the groove and has a tip portion which projects from the groove for sliding, sealing engagement with a surface of the other member. Cooperating cam surfaces are provided on the trailing side wall of the groove and the trailing side surface of the seal blade which are operable in response to forces urging the trailing side surface into contact with the trailing side wall to produce reaction force components urging the blade to extend from the groove. Coupling seal recesses are formed at opposite ends of the groove, and a coupling seal member is received in each of the recesses. The coupling seal member and seal blade are interengageable with each other in such a manner that the coupling seal members are urged to project axially from the respective coupling seal recesses while simultaneously urging the seal blade toward a centered position in the groove and to extend from the groove.

**SEALS AND METHODS AND MEANS OF SEALING
FOR ROTARY ENGINES AND THE LIKE**

This invention relates generally to seals and methods and means of sealing as related to rotary machines and is particularly concerned with seals and means of sealing for relatively moving parts of eccentric rotor engines of the type commonly referred to as "Wankel" engines although the invention is not restricted to eccentric rotary engines and will have application to other types of machines, pumps, compressors and the like.

While the problem will be generally discussed below in connection with rotary engines of the Wankel type, the present invention is concerned with any device wherein it is necessary to provide slidable seals for use with moving pressure chambers, wherein the chambers are defined by two or more relatively moving members. Moreover, the invention in its broadest aspects is concerned with confining gases or fluids between at least two zones of different pressures, and more specifically, with providing, by a sealing means and control features resistant to undesirable flow of gas or fluid from a high pressure zone to a low pressure zone between at least two relatively moving members. Therefore, the phrase "rotary engines and the like" as used herein refers not only to eccentric rotor engines of the Wankel type, but to any device having relatively movable members wherein it is necessary to provide slidable seals between the relatively movable members to confine fluids between two or more zones of differential pressures.

Eccentric rotor engines are engines of the type wherein a rotor (sometimes referred to as a "rotary piston") is eccentrically mounted within an enclosed cavity of a housing and is rotatable about its own axis, which axis is eccentric to a rotatable main shaft axis, the main shaft being mounted in the housing. The rotor cooperates with the cavity walls to define a plurality of chambers that expand and contract volumetrically as the rotor rotates within the cavity, and thereby provide the four phases of intake, compression, expansion (or ignition and expansion) and exhaust, to transmit power. The most commonly known eccentric rotor engine (not claimed as a part of this invention) is the type disclosed in U.S. Pat. No. 2,998,065 of Wankel et al. The Wankel engine includes a housing having a cavity having a surface which is commonly referred to as a "trochoidal surface", and will be so referred to herein. A rotor which may be of substantially triangular configuration, or of other configurations, is received in the cavity. The rotor has end faces extending transversely to its rotary axis, and has convex or formed sides extending between its apices. Each of the sides of the rotor cooperate with the trochoidal surface of the cavity to define a chamber, the walls of each chamber being defined by the trochoidal surface of the cavity, one of the convex or formed sides of the rotor, and the end walls of the housing that extend transversely to the trochoidal surface.

A difficult problem with rotary engines of the type discussed in the preceding paragraph is that of maintaining reliably effective sealing between chambers to contain variable and different pressures, which chambers are defined as the rotor rotates about an axis within the housing. Reliable seals must be provided between the end faces of the rotor and the opposing end wall surfaces of the housing as well as between the apex

portions of the rotor and the trochoidal surface of the housing. In conventional rotary engines of this type, the apex portions of the rotor member are provided with apex seals that are slidably mounted in retaining grooves in the rotor, the retaining grooves having sides machined in a predetermined angular relationship with radial lines that extend from the axis of the rotor to each apex of the rotor so that each apex seal moves outwardly and inwardly within its retaining groove as it sweeps along the trochoidal surface with which it is slidably engaged. Side seals are provided within the opposite end faces of the rotor and extend between the apex portions of the rotor. The side seals engage the surfaces of the end walls of the cavity fixed to the rotor housing. In order to seal the ends of the apex portions of the rotor, coupling seals are slidably mounted within the end faces of the rotor for axial movement in a direction parallel to the axis of the rotor. The coupling seals also serve as a junction seal between the side seals and apex seals. The ends of the side seals abut the coupling seals, and the apex seals are received in grooves formed in the coupling seals. The coupling seals are conventionally of cylindrical shape and are received in cylindrical openings formed radially inwardly of the respective apices of the rotor. The coupling seal face seats against the adjacent end wall surface of the rotor housing and sweeps along such surface in a trochoidal path having generally the same configuration as the trochoidal surface of the cavity as the rotor rotates within the cavity.

In present constructions, the coupling seals, side seals, and the apex seals are resiliently biased toward engagement with the respective surfaces against which they are to seal. It is important that each apex seal, side seal and coupling seal always remain in contact with their respective sealing surfaces; however, the seals should be freely movable with respect to rotor in order to accommodate surface irregularities due to manufacturing tolerances, heat distortions, wear, etc., and so that the seals will always be free for quick return movement to maintain coactive contact with their respective sealing surfaces if caused to move out of contact therewith by adverse forces. If an apex seal is caused to move out of contact with the trochoidal surface, any frictional forces tending to retard its return movement to sealing engagement with the trochoidal surface increases the amount of leakage and thus decreases the power of the engine, wastes fuel, and causes the loss of emissions control. Similarly, if a coupling seal is caused to move out of engagement with the end wall surface of the chamber, any frictional forces tending to retard its return movement to sealing engagement with the end wall surface increases (1) the amount of leakage and hence the loss of power, (2) high fuel consumption, and (3) the loss of emissions control. Further, if a side seal member is caused to move out of engagement with the end wall surface of the chamber, any undesirable frictional forces which would retard its return movement to its sealing engagement would cause leakages from its respective chamber, allowing loss of power, loss of emissions control, and waste of fuel.

With the conventional seal arrangement described in the preceding paragraphs, adverse forces exerted on the various sealing components as the rotor rotates within the trochoidal cavity tend to increase undesirable frictional contact between the apex seal, coupling seal, side seal members and apex seal grooves to

thereby retard free movement of the seals with respect to their sealing surfaces. Furthermore, the constantly changing accelerating forces acting on the apex seals due to the eccentric motion of the rotor and the trochoidal path of the apex seals tend to aggravate and cause undesirable frictional engagement and retard return motion of the seals when they are forced out of engagement with their respective sealing surfaces. It is believed that these undesirable conditions are further aggravated by the impact forces on the apex seals defining the ends of the ignition chamber upon firing due to the sudden increase of pressure which tends to force the seals radially outwardly into engagement with the trochoid surface with an amount of pressure that unduly increases the friction forces between the apex seal blades and the trochoidal surface, and that increases the likelihood of the blade coming out of contact with the trochoidal surface when the direction of the blade changes abruptly as is necessary due to the configuration of the path of movement of the apex seal blade. The intermittently high unit load pressure exerted on the apex seal blade also increases the likelihood of fatigue, damage, wear, and distortion to the trochoidal surface of the housing, reducing the life of the engine and of the apex seal, further contributing to inadequate, unreliable and unstable sealing conditions.

It is, therefore, an object of this invention to provide a construction with a sealing means between relatively movable members of a rotary engine and the like wherein the differential in the contact pressure between the surfaces of the seal members and the surfaces with which the seal members are engaged during each cycle of operation of the rotary engine or the like is minimized without losing sealing effectiveness.

A further object is to provide a construction with a sealing means that will produce a sliding seal between two members of rotary engines and the like, one of which members moves relative to the other, wherein a seal blade is received in a groove in said one member, the groove extending substantially transversely of the direction of relative movement between the two members, in which cooperating cam surfaces are provided between the groove and the seal blade, which cooperating cam surfaces are coercively responsive to forces urging the seal blade into contact with one of the side walls of the groove in such a manner as to produce advantageous reaction force components urging the seal blade to slidably cam itself outwardly from the groove to thereby maintain sealing engagement with the surface of the other member.

A further object is to provide a component sealing construction with a provision for a sealing means that will minimize the adverse effects of friction force between the drive wall of the groove and the trailing side surface of the seal blade.

A further object is to provide an apex sealing arrangement for rotary engines and the like that will minimize the shock loading on the apex seal blade caused by the intermittent and instantaneous pressure rise at ignition and explosion of the fuel without reducing the sealing efficiency of the apex seal.

Still another object of this invention is to provide an apex sealing arrangement for rotary engines and the like that will (1) increase the power output by minimizing leakage from zones of relatively high pressure to zones of relatively low pressure, (2) provide better control of the content of the exhaust emissions by reducing

the amount of unburned fuel in the emissions caused by leakage during the ignition and expansion phase of each cycle of the engine, (3) provide for greater efficiency of operation by reducing the fuel consumption without sacrificing power output, and (4) reduce the wear of the sealing components and of the housing and thereby provide a longer operating life for the sealing components and housing.

Another object of this invention is to provide an apex sealing arrangement for rotary engines and the like wherein friction forces that would normally tend to retard movement of the sealing members produce compensating reaction forces tending to urge the sealing members to move in a sealing direction without retardation.

A further object is to provide an apex sealing arrangement for rotary engines and the like wherein the high pressures on the apex seals produced by ignition of the fuel are redistributed to reduce the impact forces on the individual seals and thereby decrease the wear on the related engine parts.

A further object of this invention is to provide an apex seal assembly for rotary engines and the like including a retaining member with which the apex seal and coupling seal can be assembled together and calibrated and the entire assembly installed as a unit on the rotor of a rotary engine or the like.

A still further object is to provide an apex seal assembly for rotary engines and the like having an apex seal blade and a coupling seal member wherein the apex seal blade and coupling seal have coacting surfaces operable to produce desirable reaction components of force in response to forces ordinarily adverse to the sealing function of the assembly, which reaction component increase the sealing function of the assembly.

A still further object is to provide a rotor for a rotary engine or the like wherein the apex portions of the rotor are defined by a retaining member that is installed separately onto the rotor so that side seal grooves can be more easily cut into the rotor prior to installation of the retaining member.

A further object is to provide a rotor for a rotary engine or the like wherein the apex portions of the rotor are defined by a retaining member that is installed separately onto the rotor and which can be made of a material different from but compatible with the material of the rotor so that the retaining member does not have to meet the requirements of the rotor material in addition to the requirements of the material of the retaining member.

A further object is to provide a retaining member for installation onto the rotor of a rotary engine or the like to form an apex portion thereof, the retaining member being formed with slots for receiving the ends of side seal strips with a clearance being provided between the surface of the slots and the ends of the side seal strips to eliminate adverse friction forces between the side seal strips and retaining member and at the same time provide a baffling effect for the escapement of fluid pressure around the ends of the side seal strips without retarding movement of the coupling seals.

Still another object is to provide a rotor for a rotary engine or the like having side seals, coupling seals and apex seals wherein the coupling seals do not frictionally engage the side seals so that the side seals and coupling seals do not interfere with the sealing functions of each other, and wherein the coupling seals and apex seals

are coercively engageable with each other to urge each other toward sealing engagement with their respective sealing surfaces.

A still further object is to provide a seal blade for the apex of the rotor of a rotary engine or the like wherein the seal blade has a tip with a working surface for slideable, sealing engagement with another surface wherein the trailing portion of the working surface has a larger radius of curvature than the leading portion thereof, and which trailing portion of the blade tip is levered in the manner of a bell crank to always assure contact with the trochoidal surface of the housing and to accommodate changes in the trochoidal surface due to heat, force distortion, manufacturing tolerances, and changes in the contour of the surface engaged thereby.

A further object is to provide a seal blade for the apex of a rotary engine or the like having a cam surface formed on the trailing surface thereof for coercively engaging the trailing side wall of the groove in which it is adapted to be received in such a manner that the seal blade is urged in a direction toward the trailing side wall and outward of such groove.

Another object is to provide a seal blade for the rotor of a rotary engine or the like having a coupling seal cam surface formed thereon for coercively engaging a coupling seal member in such a manner that the seal blade and coupling seal are urged toward sealing engagement with their respective sealing surfaces by their coercive engagement.

A further object is to provide a coupling seal member for a rotary engine or the like having a cylindrical body formed with a groove for receiving an end portion of an apex seal blade, and having a seal blade contact member for coercively engaging a cam surface formed on such seal blade to produce constant reaction components of force urging the coupling seal toward engagement with the surface it is adapted to sealingly engage.

A further object is to provide a sealing construction and means of sealing for rotary engines and the like that will constantly urge outward radial forces and axial forces to resist inward forces of the sealing members when said sealing members are cooperating with sealing surface of the non-retaining seal members throughout each complete revolution of the rotating member.

Another object is to provide freely slideable sealing members for rotary engines and the like to constantly resist forces and friction that would otherwise retard the sealing members free movement in an outward direction toward the sealing surface with which they coercively cooperate.

A further object is to provide a sealing construction for rotary engines and the like that will redirect forces to contribute toward constant sealing direction of said seals to maintain engagement with the sealing surfaces irrespective of the position that the rotating member takes throughout each revolution about an eccentric axis.

A further object is to decrease the high load pressures on the working sealing surfaces of the seals of rotary engines and the like while providing free movement of the slideable members without losing sealing effectiveness or proper sealing between the seals and the cooperating members.

A further object is to provide an assembly including a pair of oppositely extending side seal slots in said coupling seal member, each of said coupling seal side seal slots being positioned in alignment with a respec-

tive one of said side seal slots in said retaining member to form an extension thereof, the respective end portions of said side seal strips being received in the slots in said coupling seal member, and wherein a clearance is always maintained between the end portions of said side seal strips and the surfaces of the respective side seal slots in said coupling seal members in all positions of said coupling seal member.

The foregoing, and further objects, are achieved in the present invention by the provision of an apex sealing assembly including an apex seal blade retaining member, an apex seal blade and a pair of opposite hand coupling seal members biased outwardly by springs. The retaining member may consist simply of the apex portion of the rotor for the rotary engine, or may be a separate member that can be installed separately onto the rotor to define the apex portion thereof. The retaining member is formed with a groove for receiving the apex seal blade, and a pair of coupling seal recesses at each end which communicate with the apex seal blade groove. The coupling seal member is formed with a contact arm that responds to frictional forces between the coupling seal and the end wall of the cavity in which the rotor is received to urge the apex seal blade toward the trailing side wall of the slot in which it is received. The apex seal blade is formed with cam surfaces on its leading side surface for engagement by the contact arms of the coupling seals to bias the coupling seals axially outwardly toward engagement with each end wall surface of the cavity. The ends of the apex seal blades are relieved on their lower portions so that any intermittent contact with the end wall surfaces of the engine cavity by the ends of the seal blade will produce forces further maintaining the apex seal blade in sealing engagement with its sealing surfaces. The trailing side wall of the slot in which the seal blade is received is formed with a cam surface, and the trailing side surface of the seal blade is formed with a cam surface (one of which may be convex and the other of which may be concave, or an inclined plane, etc.) the cam surfaces having configurations such that the seal blade contacts the trailing wall of the slot with a substantial line contact and thereby causes the apex seal blade to be urged by camming radially outwardly by such contact.

The invention also includes an embodiment wherein relief or accumulator ports are formed in the rotor and communicate with the chambers of the rotary engine through ports in the apex seal assembly, and operate to control and limit the maximum pressure caused by ignition to reduce the impact forces on the seal blades at ignition to reduce distortion of the trochoid surface of the housing and simultaneously reduce wear on the cooperating members.

Other objects, advantages and features of the invention will become apparent from the following description taken in connection with the accompanying drawings in which:

FIG. 1 is a perspective view of a rotary engine rotor and trochoidal chamber having a prior art, conventional apex sealing arrangement;

FIG. 2 is a diagram illustrating the distribution of the radial forces exerted by the apex seal on the trochoidal surface of the engine cavity, the FIG. 2 diagram illustrating the forces exerted by conventional apex seal assemblies, and one typifying a more desirable force pattern, as well as the theoretically ideal force pattern;

FIG. 3 is a view of a rotary engine diagrammatically illustrating the various positions and conditions affecting the apex seal during rotation of the rotor;

FIG. 4 is a graphical illustration of the velocity variations of each of the apex seals during rotation of the rotor;

FIGS. 5A and 5B are graphic illustrations illustrating the apex seal velocity change in relationship to the change of the rake angle of the apex seal with respect to the surface of the engine cavity;

FIGS. 6A-6E are fragmentary sectional views of an apex seal of the engine of FIG. 1 illustrating the change in the position and conditions of the seal as the seal moves along the surface of the cavity of the engine from the lefthand firing position to the right-hand firing position;

FIGS. 7 and 8 are elevational views of a typical rotary engine rotor and trochoidal chamber of the type illustrated in FIG. 1 showing the positions of the rotor creating adverse sealing conditions at the apex seal blades;

FIG. 9 is an elevational view of a rotary engine rotor and trochoidal chamber, the rotor having apex seal assemblies according to one form of the invention;

FIG. 10 is an enlarged elevational view of an apex seal assembly of the engine of FIG. 9;

FIG. 11 is a side view, on a slightly reduced scale, of the sealing assembly of FIG. 10 taken on lines 11-11;

FIG. 12 is a view on lines 12-12 of FIG. 11;

FIG. 13 is a sectional view taken on lines 13-13 of FIG. 10;

FIG. 14 is a view similar to FIG. 10 on an enlarged scale;

FIG. 14A is a sectional view, on an enlarged scale, taken on lines 14A-14A of FIG. 11;

FIG. 14B is a view illustrating the manner in which an apex seal according to the present invention tends to resist separation from the trochoid surface and cooperating sealing surfaces due to skipping and distortions in the trochoid surface as compared with one conventional apex seal construction;

FIGS. 15 through 19 are views similar to FIG. 10 illustrating the change in the position of the apex seal, coupling seal, and side seal, and illustrating sealing surfaces with the side walls of the trochoidal chamber as the seals move from the left-hand firing position to the right-hand firing position;

FIG. 20 is a perspective view of the coupling seal and spring used with the assembly of FIG. 10;

FIG. 21 is a perspective view of the apex seal blade used with an assembly of FIG. 10;

FIG. 22 is a perspective view of the apex seal retainer used with an assembly of FIG. 10;

FIG. 23 is a view similar to FIG. 10 of an apex seal assembly according to another embodiment of the invention;

FIG. 24 is a sectional view taken on lines 24-24 of FIG. 23;

FIGS. 25 and 26 are sectional views taken on lines 25-25 and 26-26, respectively, of FIG. 24;

FIG. 27 is a view similar to FIG. 9, partially in section, of a rotary engine rotor and trochoid housing according to another embodiment of the invention;

FIGS. 28, 29 and 30 are enlarged fragmentary views of each of the apex portions of the rotor of the engine of FIG. 27;

FIG. 31 is a view similar to FIG. 27 with the rotor in a different position;

FIGS. 32, 33 and 34 are enlarged fragmentary views of each of the apex portions of the rotor in the position of FIG. 31;

FIG. 35 is a view similar to FIG. 27 with the rotor in still different position;

FIGS. 36, 37 and 38 are enlarged fragmentary views of each of the apex portions of the rotor in the position of FIG. 35;

FIG. 39 is a view similar to FIG. 27 with the rotor in still another position; and

FIGS. 40, 41 and 42 are enlarged fragmentary views of each of the apex portions of the rotor in the position of FIG. 39.

The numerous adverse forces and conditions acting on the apex seals of Wankel engines will first be described in connection with FIGS. 1 through 8 in connection with conventional, prior art apex sealing assemblies.

In FIG. 1, reference numeral 20 collectively designates a rotary engine housing having a cavity 22 formed with a trochoidal surface 24 having an inwardly projecting upper lobe 28 and an inwardly projecting lower lobe 26. The cavity 22 has a central axis designated by reference numeral 21. The cavity 22 is further defined by the inner surfaces 27a and 29a of end plates 27 and 29, respectively, closing the opposite ends of the cavity. Fragmentary portions of the end plates 27 and 29 are illustrated in FIG. 1. Intake and exhaust ports 23 and 25, respectively, are illustrated in the trochoidal wall 24 of the cavity on opposite sides of the lobe 26. In some conventional rotary engines and the like, the intake and exhaust ports are formed in the end plates rather than in the trochoid surface.

Eccentrically rotatably mounted in the cavity 22 is a rotor collectively designated by reference numeral 30, the rotor 30 being of triangular configuration with convex side walls. The axis of the engine housing and cavity 22 is indicated by reference numeral 21, while the axis of the rotor is indicated by reference numeral 31. The rotor 30 includes an end face 32 disposed in opposed relationship with the surface 27a of the end plate 27, an end face 32' disposed in opposed relationship with the surface 29a of the end plate 29, and three side walls 34, the side walls being individually designated by reference numerals 34a, 34b and 34c. The apex portions of the rotor are designated by references characters X, Y and Z. The side wall 34b extends between the apex portions X and Y, the side wall 34c extends between the apex portions Y and Z, and the side wall 34a extends between the apex portions Z and X.

Mounted in the end face 32 and extending along each of the side walls between the apex portions are side seal members 36, the side seals 36 being designated individually by reference numerals 36a, 36b and 36c which are disposed adjacent to the side walls 34a, b and c, respectively. The side seals 36 are provided to sealingly engage the surface 27a of the end plate 27. The ends of the side seals engage coupling seals 38x, 38y and 38z located at the apex portions X, Y and Z, respectively. Also mounted in the apex portions are apex seal blades 40, the apex seal blades being individually designated by reference numerals 40x, y and z at the apex portions X, Y and Z, respectively. Similar side seals and coupling seals are provided on the end face 32' of the rotor to sealingly engage the end face 29a. The apex seal blades 40 engage the trochoidal surface 24 and sweep along the surface 24 as the rotor 30 rotates

within the cavity 22. In the engine of FIG. 1, the apex seals 40 are each located along a radius R of the rotor 30, each radius R extending from the center line axis 31 of the rotor 30. The center line axis 31 of the rotor is eccentric to the axis 21 of the housing.

In FIG. 1, the rotor is shown in the firing or ignition position, and the cavity 22 is divided into an ignition and expansion chamber 42, an exhaust chamber 44, and an intake and compression chamber 46. The ignition chamber 42 is defined by the portion of the trochoidal surface 24 that extends between the apex seal blades 40z and 40x, the side wall 34a of the rotor and the end surfaces 27a and 29a of the end plates 27 and 29. The gases in the ignition chamber 42 are thus confined by the apex seals 40z and 40x, the coupling seals 38z and 38x, the side seal 36a, and the side seal corresponding to the side seal 36a on the end face 32'.

The exhaust chamber 44 is defined by the portion of the trochoidal surface 24 that extends between the apex seals 40x and 40y in the rotor position of FIG. 1, the side wall 34b, and the end surfaces 27a and 29a. Similarly, the intake chamber 46 is defined by the portion of the trochoidal surface 24 that extends between the apex seal blades 40y and 40z, the side wall 34c, and the end surfaces 27a and 29a. As the rotor 30 rotates in a clockwise direction as indicated by the arrow 48 in FIG. 1, the engine passes through the four cycles of intake, compression, expansion (or ignition and expansion) and exhaust due to the configuration of the trochoidal surface 24 and the eccentric relationship of the rotor 30 within the housing.

In the engine shown in FIG. 1, the ends 50 of the apex seals 40x, y and z may intermittently contact the surfaces 27a and 29a. As the rotor rotates within the cavity, the angular velocity of the ends 50 of the apex seals is greatest at the point where the apex seal contacts the trochoidal surface 24, that is to say, the angular velocity along the length of the end 50 of the apex seals 40 increases as the distance from the axis of rotation of the rotor increases. Consequently, the outer tip of each of the ends 50 has a greater angular velocity than the portion received in the slot in the coupling seal 38, which in turn tends to impart rotation to the coupling seals and apex seals in the directions of arrows 52 due to the increased frictional drag at the outer tip of the ends 50 of the respective apex seals. Consequently, the coupling seals 38 tend to dig into the sides of the apex seal blades 40 to create a high degree of friction forces between the apex seal blades and the coupling seal. The friction forces tend to retard free movement of the blades 40 outwardly in the direction of the rotor radii R, and to similarly retard outward motion of the coupling seals 38 in a direction parallel to the axis of rotation of the rotor.

In the position of the rotor shown in FIG. 1, the engine is in the firing position. The apex seal blade 40x constitutes the leading end of the expansion chamber 42 and the trailing end of the exhaust chamber 44. The apex seal blade 40y constitutes the leading end of the exhaust chamber 44 and the trailing end of the intake chamber 46, while the apex seal 40z constitutes the leading end of the intake chamber 46 and the trailing end of the ignition chamber 42. As the rotor rotates in the direction of arrow 48 in FIG. 1, the apex seal 40x sweeps along the trochoidal surface 24 during the expansion phase until it sweeps past the exhaust port 25 whereupon the chamber defined between the apex 40x

and 40z immediately converts from the expansion chamber to the exhaust chamber. Simultaneously, the chamber defined between the seals 40y and 40z moves into the intake and compression position, and when the seal 40z reaches the position occupied by the seal 40x in FIG. 1, the ignition and expansion chamber 42 is defined between the seals 40y and 40z with the seal 40z defining the leading end of the expansion chamber 42. The intake chamber is then defined between the seals 40x and 40y. During this movement of the rotor within the cavity 22, the apex seals 40x, y and z and coupling seals 38x, y and z are subjected to many forces tending to resist the sealing action and thereby to produce leaks resulting in power losses in the engine. Some of the adverse forces and conditions opposing proper sealing contact between the apex seal side surface and apex seal groove wall, and between the apex seal working tip and the trochoid surface 24, and between the coupling seals 38x, y and z and the end plate surfaces 27a, 29a are:

1. the vibration or alternating forces caused by the backlash on the timing gear which is particularly acute at at least two stages, namely, at ignition which causes a sudden reversal of forces on the timing gear, and when the leading apex seal of the expansion chamber passes the exhaust port to also cause the forces on the rotor and hence the load on the timing gear to reverse;
2. the acceleration and deceleration forces on each apex portion of the rotor during each revolution of the rotor;
3. the variation in the rake angle of each apex seal blade with respect to the trochoid surface;
4. the abrupt changes in the direction of movement of the apex seal blades particularly as the blade sweeps past the upper lobe 28;
5. the abrupt increase in friction forces and unit load pressure at ignition brought about by the sudden increases in forces urging the seals at the ends of the ignition and expansion chamber into contact with the trochoidal surface;
6. the friction forces between the apex seal blade and the coupling seal which tend to retard return movement of the apex sealing blade and coupling seal when the seals are driven out of contact with their respective sealing surfaces, as well as the friction forces between the ends of the apex seal blades and the surfaces 27a and 29a;
7. the unit load or force between the tip of the seal blade and the trochoid surface varies at each position of the blade along the trochoid surface; therefore, the friction force between the tip of the seal blade and the trochoid surface varies at each position of the seal blade along the trochoid surface; and
8. the trochoid surface expands and contracts and is otherwise distorted due to temperature changes and variable forces causing the lobes 26 and 28 to move toward and away from each other which requires that the seal blade be freely movable in a radial direction to follow the surface of the trochoid, this condition being further aggravated by non-uniformity in the sealing surfaces caused by manufacturing tolerance variations.

An analysis of the adverse conditions will now be discussed primarily in connection with FIGS. 3 through 9.

In FIG. 3, the rotor 30 is shown in the full line position with the apex X located at the upper lobe 28. As in FIG. 1, the axis of the engine housing is shown at 21 in FIG. 3, and the axis of the rotor 30 in the full line position is indicated by reference numeral 31. The center of rotary axis 31 of the rotor moves in a circular path, indicated by reference numeral 54, about the axis 21. The rotor rotates with a substantially uniform velocity about its axis 31; however, since the distance between the apex portions and the axis 21 varies because of the eccentricity, the apex portions accelerate and decelerate during each revolution of the rotor about the axis 21. When an apex portion is located at either of the lobes 26 or 28, such apex portion is located at its shortest radial distance from the axis 21, and consequently, the angular velocity of each apex portion is at a minimum when the apex portion passes the lobes 26 and 28. Thus, in FIG. 3, the apex portion X in the full line position 30 of the rotor is at a position of minimum angular velocity.

When an apex portion is located at the diametrically opposed points 56 and 58 between the lobes 26 and 28, or at 90° angular locations from the lobes 26 and 28, the apex portion at either point 56 and 58 is at its longest radial distance from the axis 21, and hence the angular velocity of such apex portion is at its maximum. For example, the apex portion Z in the phantom line position 30a of the rotor in FIG. 3 is located at point 58; hence, the apex portion Z at point 58 has its maximum angular velocity about the axis 21.

Since points 56 and 58 on the trochoid surface 24 are points of maximum angular velocity of the apex seals, and since the lobes 26 and 28 are points on the trochoid surface 24 of minimum angular velocity of the apex portions, an apex portion accelerates as it moves from lobe 26 to point 58, decelerates as it moves from point 58 to lobe 28, accelerates as it moves from lobe 28 to point 56, and decelerates as it moves from point 56 to lobe 26. In FIG. 3, the quadrant between lobe 26 and point 58 is indicated to be quadrant D, the quadrant between point 58 and lobe 28 is indicated as quadrant E, the quadrant between lobe 28 and point 56 is indicated to be quadrant F, and the quadrant between point 56 and lobe 26 is indicated to be quadrant G. An apex portion accelerates as it moves through quadrants D and F, and decelerates as it moves through quadrants E and G. Thus, quadrants D and F are acceleration quadrants, while quadrants E and G are deceleration quadrants.

The variations in acceleration and velocity of the apex portions during rotation of the rotor 30 is further illustrated in FIG. 3 in that zones A, A', B' and B are equal time zones, that is, the time required for an apex portion of the rotor to move along the trochoid surface 24 from one end to the other of zone A is the same as the time required to move through zone A', and is also the same as the time required to move through zones B' and B. Similarly, the angles 60, 62, 64 and 66 in FIG. 3 define equal time zones. Hence, in the full line position 30 of the rotor in FIG. 3, the time required for the apex portion Z to move through the angle 60 is equal to the time that will subsequently be required for the apex portion Z to move through the angle 64, and is also equal to the time required for the apex portion Z to subsequently move through each of the angles 62 and 66.

The path of movement of an apex portion of the rotor around the trochoid surface 24 approaches, or is similar to in some respects to a rectangular path of movement. A simulated rectangular path is shown in phantom lines and indicated generally by reference numeral 61 in FIG. 3. The left side of the rectangular path 61 is indicated by reference numeral 61-A and extends between the ends of zone A. The upper side of the rectangular path 61 is divided into two equal segments, 10 namely, segment 61-A1 extending between the ends of zone A1, and a segment 61-B1 extending between the ends of zone B1. The right-hand side of the rectangular path 61 is indicated by reference numeral 61-B and extends between the ends of zone B. The lower side of the rectangular path 61 is designated by reference numeral 61-C and extends from the lower end of zone B to the lower end of zone A.

The simulated rectangular path 61 graphically illustrates that each apex portion of the rotor abruptly changes direction as it moves from zone A to zone A1, and from zone B1 to zone B. Furthermore, the simulated rectangular path 61 further clearly illustrates that the straight line distance along side 61-A between the ends of zone A is greater than the straight line distance along the segment segment 61-A1 between the ends of zone A1 although the time required for an apex portion to move through zone A is the same as the time required for the apex portion to move through zone A1.

The abrupt change of direction of the apex portion as it moves from zone A to zone A1 abruptly increases the acceleration force components in the direction of the upper side of the rectangular path 61 including segments 61-A1 and 61-B1 and abruptly decreases the acceleration force components in the direction of the side 61-A.

18 Eighteen positions of the apex seal Z are illustrated in phantom lines between points 58 and 56, or the apex seal Z of rotor 30a moves through quadrants E and F. As the apex portion Z moves past position 3 at the end of zone A and the beginning of zone A1, the rather abrupt change in direction will increase the friction between the left or trailing side of the apex seal and the drive or trailing side wall of the groove.

To the extent that the rate of movement of an apex seal in the horizontal direction along segments 61-A1 and 61-B1 is greater than the rate of movement upwardly in a vertical direction as viewed in FIG. 3, there is a tendency for the apex seal to separate from the trochoid surface 24. Furthermore, as the apex seal moves through zone B1 in quadrant F, the radial distance of the apex seal from the axis 21 must increase in order for the apex seal to maintain contact with the trochoid surface 24, i.e. the trochoid surface 24 tends to fall away or move from the apex seal. (As the apex seal moves through quadrants D and F, the radial distance between the axis 21 and the trochoid surface 24 increases, while the opposite is true with respect to quadrants E and G; in quadrants E and G, the radial distance between axis 21 and the trochoid surface decreases from point 58 to point 28, and from point 56 to point 26.) This condition is particularly aggravated in zone B1, and even more so in zone J, because of heat and force distortions of the trochoid surface 24 that further increases the distance between the trochoid surface 24 and the axis 21.

The velocity variations of the apex seals X, Y and Z during a full revolution of the rotor is graphically illus-

trated in FIG. 4. In FIG. 4, the length L of the graph corresponds to a 360° rotation of the rotor 30 while the height H of the graph represents the rate or percent of increase in velocity of an apex seal from the minimum velocity. The paths of the various seals are plotted from the position of the rotor 30 shown in full lines in FIG. 3 with the apex portion X located at the upper lobe 28. Clockwise rotation in the direction of arrow 48 (FIG. 3), as graphically illustrated in FIG. 4, causes the seal X to accelerate from its minimum velocity at the lobe 28 to a maximum velocity of slightly more than 140% of the minimum velocity as it reaches point 56 in the trochoid surface 24 after 90° rotation from the full line position of FIG. 3. The seal X then decelerates from point 56 as it moves along the trochoid surface 24 to the lobe 26 after 180° angular movement from the full line position shown in FIG. 3. The seal X then accelerates as it moves from lobe 26 to point 58 to a velocity of slightly more than 140% of the minimum velocity at 270° rotation of the rotor from the full line position in FIG. 3. The seal X then decelerates during the final 90° rotation as it returns to the minimum velocity position at lobe 28. Seal Z reaches its first point of maximum velocity at point 58 after approximately 30° rotation from the full line position shown in FIG. 3, and during the same period of time, the seal Y is decelerating as it moves toward lobe 26 which it reaches after 60° rotation from the full line position of FIG. 3. As FIG. 4 illustrates, each apex portion has a different angular velocity at each angular position of the rotor 30 about the axis 21. The arrows 67 in FIG. 4 indicate acceleration of each of the apex seals X, Y and Z, while the arrows 68 indicate deceleration of the respective seals X, Y and Z.

FIG. 3 also illustrates that the "rake angle" of each of the apex seals changes as the seal sweeps along the trochoid surface 24. By "rake angle" is meant the angle between the radius R of the rotor at the apex with the trochoid surface 24. The rake angle is positive when the friction force between the apex seal and the surface 24 has a component tending to push and scoop the apex seal radially inwardly toward the central axis 31 of the rotor, and is negative when the friction force has a component tending to urge the apex seal radially outwardly from the axis 31. The rake angle of an apex portion is neutral, or zero, when the apex portion is at either of points 25, 58, 28 or 56 on the surface 24. Thus, the rake angle of the apex portion Z of the rotor in the phantom line position 30a in FIG. 3 is zero since the apex portion Z is located at the point 58. As pointed out above, eighteen positions of the apex portion Z are illustrated in phantom lines between the point 58 and point 56, or as the apex portion Z moves through the quadrants E and F. At positions 1 through 8 in quadrant E, the rake angle is negative, while at positions 10 through 17 in quadrant F, the rake angle is positive. The rake angle changes from negative to positive as the seal sweeps past the lobes 26 or 28.

FIGS. 5A and 5B illustrate the correspondence between the rake angle and acceleration of an apex seal during a single revolution of the rotor. In the graph of FIG. 5A, the length L of the graph represents 360° rotation of an apex seal while the height H represents the rate of percent of increase in velocity of the apex seal from the minimum velocity at the lobes 26 and 28. FIG. 5B illustrates the rake angle of the apex seal during the 360° rotation, the trochoid surface 24 being repre-

sented in the diagram of FIG. 5B as a straight line. The eighteen positions in quadrants E and F are marked off along the upper portion of the graph of FIG. 5A, and the rake angles at the respective positions are indicated directly above these positions in the diagram of FIG. 5B. Thus, at the lobe 28, minimum velocity is indicated in FIG. 5A, and zero rake angle is indicated in FIG. 5B at lobe 28. The rake angle is illustrated at the various positions in each of the quadrants D, E, F and G in FIG. 5B. The maximum rake angle in quadrant F occurs at positions 12 and 13 and is approximately 25° in both of these positions. FIGS. 5A and 5B also illustrate that the rake angle is positive in quadrants D and F, and that the rake angle is negative in quadrants E and G. The extent of the positive rake zones can be reduced somewhat by tilting the apex seal blade and its groove in the negative rake direction with respect to the radial lines through the apices from the axis 31 of the rotor.

Since a positive rake angle produces a friction force component tending to push the apex seal radially inwardly, or out of engagement with the trochoid surface 24, there is a greater likelihood of leakage past an apex seal when the rake angle is positive than is the case when the rake angle is negative. Furthermore, the friction force component tending to push the apex seal radially inwardly and disengage it from the trochoid surface 24 increases with increases in the velocity of the apex seal along the trochoid surface. Thus, the tendency for leakage to occur is aggravated when the apex seal is in an area along the trochoid surface 24 in which the acceleration is at its maximum together with a maximum positive rake angle. These two areas are illustrated in zones J and K on FIG. 3, as well as the diagram of FIG. 5B.

It is believed that the tendency of the apex seal to fail due to the combination of acceleration and positive rake angle is further aggravated in zone J due to the forces on the seal in an expansion phase of the engine. It is believed that the high pressures acting on the seal, together with the sudden change of direction and rake angle as the apex seal passes over the upper lobe 28 creates a tendency for the seal to "skip" into and out of engagement with surface 24 as it passes from the lobe 28 through zone J. This tendency is illustrated in FIGS. 6A through 6E.

In the position illustrated in FIG. 1, the apex seal 40z is in the left-hand ignition position and the apex seal 40x is in the right-hand ignition position. FIG. 6A illustrates the apex seal 40z in the left-hand firing or ignition position. FIG. 6E illustrates the right-hand firing position of the apex seal 40z, or the position of the apex seal 40z after it has moved from the position shown in FIG. 1 to the position occupied by the apex seal 40x in FIG. 1. FIGS. 6B, 6C and 6D illustrate intermediate positions of the apex seal 40z as it moves from the left-hand firing position to the right-hand firing position, FIG. 6C illustrating the position of the apex seal 40z as it contacts the lobe 28.

The apex portion Z is shown in enlarged detail in FIG. 6A. The apex seal 40z is received in a groove 70 formed in the coupling seal 38z and coextensive with a groove formed in the apex portion of the rotor 30. The leading side wall of the groove 70 is indicated by reference numeral 70a, while the trailing side wall, or driving side wall, is indicated by reference numeral 70b. A spring 69 urges the seal 40z outwardly along the radius R into engagement with the surface 24 of the

cavity 22. When the apex seal 40z is in the left-hand firing position illustrated in FIG. 6A, ignition of the gases in the ignition and expansion chamber 42 causes a sudden increase in the pressure in chamber 42 which pressure flows through the space between the seal blade 40z and the leading side wall 70a of groove 70 and urges the apex seal 40z toward the left into engagement with the trailing side wall 70b as indicated by the arrow 72 in FIG. 6A, and outwardly along the radius R as indicated by the arrows 73 in FIG. 6A since the pressure in chamber 42 greatly exceeds the pressure in compression chamber 46. The contact point between the outer edge of the apex seal 40z and the surface 24 is indicated by reference numeral 71. In FIG. 6A, the contact point 71 is angularly displaced from the radius R by an angle w which, in the position shown in FIG. 6A is approximately 17°, assuming a constant radius for the tip of the blade, the radius having a center at 71e. The pressure in the direction of arrows 73 exerted by the ignition of the gases in chamber 42 instantaneously increases the contact pressure between the apex seal 40z and surface 24 and hence the friction forces between the apex seal 40z and surface 24 as the seal moves toward the right in FIG. 6A as illustrated by the arrow 48. In FIG. 6a, the rake angle is negative such that the friction force component parallel to the radius R is in a direction to urge the seal 40z toward engagement with the trochoid surface 24.

In FIG. 6B, the apex seal 40z is in a position approximately midway between the left-hand firing position and lobe 28. In FIG. 6B, the negative rake angle of the seal 40z has increased, and the angle w between the contact point 71 and the radius R has increased to approximately 26°. The position shown in FIG. 6B corresponds approximately with position 6 shown in FIGS. 3, 5A and 5B in which the negative rake angle is approximately 25°. Thus, FIG. 6B is the approximate position on the left-hand side of the lobe 28 in which the contact angle w and negative rake angle is at a maximum.

FIG. 6C illustrates the apex seal 40z in the center position at the lobe 28, which position corresponds to position 9 in FIGS. 3, 5A and 5B. The rake angle is neutral or zero, and the contact point 71 is at the tip of the apex seal along the radius R. The apex seal 40z in FIG. 6C still defines the trailing end of the expansion chamber 42, however, the neutral rake angle and reduced unit loading between the seal blade and the trailing side 70b of the groove increases the likelihood of leakage from chamber 42 between the blade and the trailing or left-hand side wall of the groove.

In FIG. 6D, the seal 40z has moved past the lobe 28 to a position corresponding approximately to positions 12 or 13 in FIGS. 3, 5A and 5B. The rake angle has changed from negative to positive as the seal moves past the lobe 28. In FIG. 6D, the seal is in zone J of FIGS. 3 and 5B. The combination of the change of direction of the seal as it moves past the lobe 28, the high positive rake angle, and acceleration forces on the seal, together with the vibration forces caused by the backlash on the timing gears which is at a maximum when the seal is in zone J, tends to cause the seal 40z to move out of engagement with the surface 24 to provide a leakage gap g between the expansion chamber 42 and the compression chamber 45 as indicated by the arrow 74 in FIG. 6D. As pointed out previously, as the seal moves past the lobe 28 through the zone J, the forces

acting on the seal tend to cause the apex seal 40z to skip or bounce along the surface 24 to create the leakage gap g illustrated in FIG. 6D.

In FIG. 6E, the seal 40z has reached the right-hand firing position, that is, the position corresponding to the position of seal 40x in FIG. 1. In the right-hand firing position, the seal 40z has become the trailing end of the exhaust chamber 44 and the leading end of the ignition and expansion chamber 42. The high pressure from compression and explosion has shifted with respect to the seal 40z to the left-hand side of the seal so that the seal is urged by the pressure forces indicated by arrows 72 and 73 toward the right-hand leading side wall 70a of the groove 70. The contact point 71 has shifted to the left-hand side of the radius R and the angle w in FIG. 6E is the same as the angle w in FIG. 6A.

The many forces acting on the seal blade 40z include centrifugal forces, spring pressure from spring 69, and the high compression pressure and the high ignition and explosion pressure in the expansion chamber 42 acting in the direction of arrows 73, all urging the seal blade 40z outwardly to create a sealing pressure between the tip of the seal blade and the trochoid surface. Additional forces acting on the seal blade 40z in opposition to the forces urging the seal blade 40z outwardly into engagement with the trochoid surface 24 includes the friction forces between the coupling seal 38z and the seal blade 40z, and between the side walls of the groove 70 and the side surfaces of the seal blade 40z, which later forces retard radial movement of the seal blade 40z and thus tend to produce an erratic response of the seal blade 40z to forces in the direction of the radius R. The trailing side wall 70b of the groove 70 engages the trailing side surface of the seal blade 40z and drives the seal blade 40z as it moves along the trochoid surface 24. Acceleration of the rotor thus increases the pressure between the trailing or drive wall 70b and the seal blade 40z to thereby increase the friction forces between the side wall 70b and the side surface of the seal blade 40z. Thus, the constantly varying velocity of each apex portion produces a constantly varying friction force that retards free radial movement of the seal blade along the radius R and produces an erratic response of the seal blade to forces adverse to the sealing function of the seal blade 40z.

As pointed out previously, the tendency for the condition illustrated in FIG. 6D to occur is increased by the vibration or alternating forces caused by the backlash of the timing gear which vibration forces are particularly intense as the apex seal sweeps through the zone J. FIGS. 7 and 8 illustrate the two positions of the rotor in the cavity 22 at which the backlash vibration forces are at a maximum. As shown in FIGS. 7 and 8, the rotor 30 is formed with a ring gear 78 having teeth 79 which mesh with the teeth 77 of a stationary timing gear 76. The timing gear 76 is fixed to the engine housing and is coaxial with the axis 21 of the engine housing. The ring gear 78 and timing gear 76 have been omitted from FIG. 1 for purposes of clarity of illustration. Each of the teeth 79 of the ring gear 78 has a leading flank 79a and a trailing flank 79b. Similarly, each of the teeth 77 of the timing gear 76 has a leading flank 77a and a trailing flank 77b. When the gas pressure on the rotor is in a direction to urge the rotor in a clockwise direction about the axis 21, the leading flanks 79a of the teeth 79 of the ring gear are urged into engagement with respective trailing flanks 77b of the timing gear teeth. Conversely,

when the gas pressure on the rotor is in a direction to urge the rotor in a counterclockwise direction, the trailing flanks 79b of the ring gear teeth will be urged to engage respective leading flanks 77a of the timing gear teeth. In either pressure condition, there will be an angular vibration or oscillation between the rotor and timing gear 76 from the backlash between the teeth 77 and 78, the magnitude of which will depend upon the manufacturing tolerances or clearances between the mating teeth. The backlash imposes constantly reversing acceleration forces tending to unseat the apex seal blades.

In FIG. 7, the rotor is shown in its full line position at 30 just prior to reaching the ignition position, and the compressed gases exert pressure in the direction of arrows 80 as the rotor approaches a full compression phase. Hence, the gases, exerting pressure in the direction of arrows 80, tend to urge the rotor in a counterclockwise direction with respect to the timing gear 76 so that the trailing flanks 79b of the ring gear teeth are urged by the gas pressure into engagement with the leading flanks 77a of the timing gear teeth.

In the phantom line position of the rotor at 30b, the rotor has just moved past the ignition position and is in an expansion phase. The direction of the gas pressure has shifted in the direction indicated by arrows 82 to urge the rotor in a clockwise direction with respect to the timing gear 76. Consequently, the pressure has shifted from between the trailing flanks 79b of the ring gear teeth and leading flanks 77a of the timing gear teeth to between the leading flanks 77a of the ring gear teeth and trailing flanks 79b of the timing gear teeth. This shift occurs as the rotor moves through the angle indicated at zone M in FIG. 7. Thus, there is an instantaneous, severe relative angular movement between the rotor and the timing gear 76 for the full amount of the dimensional tolerance or clearance between the particular teeth 77 and 78 in engagement with each other when the pressure forces reverse from the direction indicated by arrows 80 to the direction indicated by arrows 82, the magnitude of which depends upon the tolerances between the ring gear teeth 79 and timing gear teeth 77.

This same condition occurs when the rotor moves through the angular zone N as illustrated in FIG. 8. The angular zone N includes the timing gear teeth which, when engaged by the ring gear, are subjected to the sudden reversal of forces. Similarly, the angular zone M in FIG. 7 encloses the timing gear teeth that are subjected to the sudden reversal of forces when engaged by the ring gear teeth.

In FIG. 8, the full line position of the rotor at 30 is the position of the rotor just prior to termination of the expansion phase. The phantom line position of the rotor at 30c is the position of the rotor as it moves from an expansion to an exhaust phase. In the full line position 30 of the expansion phase, the gas pressure is in the direction of arrows 84 and urges the rotor in a clockwise direction with respect to the timing gear 76. In the phantom line position of the rotor at 30c, the gas pressures are in the direction of arrows 86 and urge the rotor in a counterclockwise direction with respect to the timing gear 76. Consequently, as the rotor moves from the expansion phase to the exhaust phase, the sudden reversal of pressures intensifies the vibration between the rotor and timing gear. It should be noted that the condition illustrated in FIG. 8 occurs as an apex

seal moves into zone J of FIG. 3 which is also the approximate position of the apex seal 40z in FIG. 6D.

Again referring to FIGS. 6A through 6E, any force that tends to retard free movement of the apex seal 40z along the radius R tends to increase the likelihood of an amount of leakage since, in order to remain in contact with the trochoid surface 24, the apex seal 40z must be freely movable along the radius R to accommodate irregularities in the surface 24 as well as the changes in contour at, for example, the lobes 26 and 28. For similar reasons, the coupling seal 38z must be freely movable in a direction parallel to the rotary axis 21 or leakage will occur between the surface 27a and the coupling seal 38z. The same is true of the side seal strips 36a and 36c. However, as indicated by the arrow 52, rotation of the rotor in the direction of arrow 48 in FIGS. 6A-6E tends to produce a counterclockwise rotation of the coupling seal 38z which tends to create frictional engagement between the coupling seal 38z and the ends of the side seals 36a and 36c, as well as between the apex seal 40z and the side walls of the groove 70. The increased frictional engagement between the parts increases the likelihood of leakage since, each time one of the members come out of engagement with its sealing surface, the frictional engagement with the other seal members retards return movement of the sealing member toward sealing engagement with its sealing surface. Furthermore, the high unit loading toward the left in FIG. 6A on the apex seal 40z tends to increase the frictional engagement between the left side surface of the apex seal and the side wall of the groove 70. In FIG. 6C, with the apex seal engaged with the lobe 28 and having a zero rake angle, the unit loading between the left side surface of the apex seal and the left side wall of the groove 70 is reduced which increases the likelihood of leakage from the expansion chamber 42 through the groove 70 around the apex seal 40z. Thus, the conventional construction shown in FIGS. 1 and 6A-6E produce friction forces that tend to retard the free movement of the side seals, coupling seal and apex seal necessary to provide good sealing action during rotation of the rotor in the cavity 22. Furthermore, there are numerous manufacturing and assembly problems associated with the conventional construction of FIGS. 1 and 6A-6E.

FIG. 2 illustrates diagrammatically the radial force between the apex seals and the trochoid surface 24 at each position of an apex seal during a complete revolution of the rotor. In FIG. 2, the curve 88 represents the radial force distribution of an apex seal of conventional construction of the type illustrated in FIGS. 1 and 6A-6E as it moves around the surface 24. Point 88a on curve 88 represents the maximum radial force between the apex seal and the surface 24 when the apex seal is in the left-hand firing position. The radial force decreases to a minimum at 88c as the seal moves past the lobe 28 which indicates a likely leakage point along the path of the seal. The radial force again increases to a maximum as the seal moves to the right-hand firing position at point 88d. The radial force decreases from the maximum indicated at point 88d to a lower pressure as indicated on portion 88e of the curve 88 as the seal moves from the expansion through the exhaust and intake phases. The curve 88 indicates a radial force pattern wherein the forces developed at ignition are greater than necessary to maintain adequate sealing. As pointed out previously, it is believed that the excessive

distortions of the trochoid housing surface caused by radial forces illustrated at points 88a and 88d creates conditions adverse to sealing and particularly enhances the likelihood of leakage at the position such as indicated in the area beyond point 88c on curve 88 (zone J of FIG. 3).

Curve 91 represents the theoretically ideal force pattern on the trochoid surface 24 wherein there is a uniform force distribution exerted by the apex seals throughout a full revolution of the rotor. Consequently, the theoretical curve 91 should be substantially concentric with the trochoid surface 24.

Curve 90 represents a more desirable radial force pattern than curve 88 (and one that more closely approaches the theoretically ideal pattern represented by curve 91) for the apex seals in that the peak force at the firing points 90a and 90d on curve 90 are reduced from the corresponding portions of curve 88, while the minimum radial forces at portions 90c and 90e along the curve 90 are increased over the corresponding areas of the curve 88 so that an adequate, but not excessive, radial contact force is maintained throughout each revolution of an apex seal. Thus, FIG. 2 represents the actual radial force pattern on curve 88 of the conventional, prior art apex seal construction, while the curve 90 represents a more desirable radial force pattern for apex seals for the type of engine illustrated in FIG. 1. The force pattern of curve 90 is more desirable because the range of forces, or the differential between the maximum and minimum forces are reduced as compared with curve 88. It is believed that the present invention as illustrated in FIGS. 9 through 42 and as described in detail below, more closely approximate the type of radial force pattern shown by curve 90 in FIG. 2.

An apex seal assembly according to one embodiment of the present invention is illustrated in FIGS. 9 through 22. FIG. 9 illustrates an engine identical to the engine of FIG. 1 except that the rotor incorporates an apex seal construction according to the invention. Accordingly, the same reference numerals as applied to the engine housing are applied to the engine housing in FIGS. 9-22; different reference numerals are applied only to the rotor and apex sealing members carried thereby in the embodiment illustrated in FIGS. 9-22. Eccentrically, rotatably mounted within the cavity 22 is a rotor 110. Rotor 110 has two end faces indicated by reference numeral 112, and side surfaces 114 extending between apex portions 118, the side surfaces 114 being substantially convex as are the corresponding surfaces in FIG. 1. Mounted in the end face 112 are side seal strips 116 which extend between apex seal assemblies 119 mounted in the apex portions 118 of the rotor.

With reference to FIGS. 10 through 14A, the apex seal assembly 119 includes a retaining member 120, coupling seal members 122, an apex seal blade 124, an apex seal spring 126, and conventional coupling seal springs 128.

The retaining member is shown in FIGS. 9 through 22 as a separate part of the rotor. It can, of course, be omitted, with the grooves and recesses for the apex seal blade 124 and coupling seals 122 formed directly into the structure of the rotor 110. However, as is pointed out in greater detail below, the housing of the apex seal blade 124 and coupling seal members 122 in a separate retaining member 120 that can be installed separately

onto the rotor facilitates the assembly and calibration of the sealing assembly, and also facilitates the manufacture of the rotor, and in particular, facilitates the forming of the grooves in the end face of the rotor in which the side seals 116 are mounted.

The rotor 110 is formed with a recess 133 at each apex portion complementary to the external configuration of the retaining member 120. The retaining member 120 may be inserted into the recess 133 by any conventional holding means and is formed with outwardly projecting portions 130 having an upper surface engageable with a complementary shoulder 132 of the recess 133 to prevent any rotatory movement of the retaining member 120 in the recess 133. The retaining member is also formed with an apex seal blade receiving groove 134 having a leading side wall 136, a trailing side wall 138, and a bottom wall 140 extending between the lower edges of the side walls 136 and 138. Formed at each end of the retaining member 120, and communicating with the groove 134, are coupling seal recesses 142 each having an end wall 144. Slots 146 are formed in the ends of the retaining member 120 for receiving the ends of the side seal strips 116. As is more clearly illustrated in FIG. 14, a clearance is provided between the side seal strip 116 and the walls of the slot 146 so that the side seal strips 116 are never in contact with the walls of the respective slots 146.

With reference primarily to FIGS. 14 and 14A, the trailing side wall 138 of the groove 134 is formed with a convex ramp portion or cam surface 148 having a radius R2. The leading side wall 136 is convex substantially throughout its length. The trailing side wall 138 has a slightly concave portion 150 that extends from the lower end of the convex portion 148 to a straight portion 152 extending upwardly from the bottom wall 140 of the groove at an angle to portion 150. Extending outwardly from the upper edges of the leading and trailing side walls 136 and 138 are inclined outer surfaces 154 and 156, respectively, which merge with and form continuations of the side surfaces 114 of the rotor to define the apex portion of the rotor.

Portion 150 of the trailing side wall cooperates with the trailing lower edge 162a of the trailing side surface 162 of the apex seal blade 124 to urge the seal blade outwardly of the groove when the lower edge 162a of the trailing side surface contacts camming surface 150. Although, as pointed out in greater detail below, during operation, the apex seal blade 124 is normally urged to the position shown in FIG. 14A wherein there is a space between surfaces 150 and 176, contact between the lower edge 162a and camming surface 150, in conjunction with the cooperation between the cam surfaces 174 and 148, tend to urge the apex seal blade outwardly of the groove.

With reference primarily to FIGS. 14, 14A and 21, the apex seal blade 124 includes outer ends extending between a leading side surface 160 and a trailing side surface 162, the outer ends having upper surfaces 158 and lower, relieved surfaces 159 (FIG. 13). The seal blade has a bottom recessed portion 164 extending between depending spring support members 166, and a tip portion 168 extending between the upper edges of the leading and trailing side surfaces and throughout the length of the blade. The tip portion of the blade has a working surface defined between the angle b (FIG. 14 and FIG. 21) having a leading portion 170 engageable with the trochoid surface 24 (FIG. 9) when the rake

angle of the blade is negative, and a trailing portion 172 which engages the trochoid surface (FIG. 9) when the rake angle of the blade is positive. The leading portion 170 of the working surface is defined by the angle b_2 , and the trailing portion 172 is defined by the angle b_1 . In the illustrated embodiment of FIG. 14, the angle b_1 defines a larger working surface than the angle b_2 , and hence the trailing portion 172, in the illustrated embodiment has a larger area than the leading portion 170 of the working surface of the blade tip.

The leading side surface 160 of the apex seal blade 124 is concave substantially throughout its length to the recessed bottom portion 164. The trailing side surface 162 has an upper, concave portion, or cam surface 174, with a radius of curvature R1 (FIG. 14) which is larger than the radius of curvature R2 of the convex portion 148 of the trailing side wall of the groove. The lower portion 176 of the trailing side surface is slightly convex and this is complementary with the lower portion 150 of the trailing side wall of the groove.

As alluded to above, the outer ends of the seal blade each has an upper portion that can, as will be pointed out below in greater detail, intermittently contact the respective surfaces 27a and 29a (FIG. 1), as well as a lower relieved surface 159 that extends from the contacting portion 158 toward the opposite end of the blade so that it will always remain out of contact with the respective surfaces 27a and 29a. Consequently, the surface 158 only can come into frictional engagement with the respective end wall surfaces of the cavity 22.

Formed on the leading side surface 160 of the seal blade 124 at the opposite ends near the upper edge are coupling seal cam surfaces 178 which are inclined inwardly toward the working surface of the blade to the end surface 158. By "inclined inwardly" is meant that the coupling seal cam surfaces are inclined in a direction to reduce the width of surfaces 158 of the ends of the blade.

With reference to FIG. 20, each coupling seal 122 includes a cylindrical body 180 formed with an elongated groove 182 for receiving the apex seal blade 124. When the coupling seal is received in the coupling seal recess 142 of the retaining member 120, the groove 182 is co-extensive with the groove 134 of the retaining member, but is larger in width than the groove 134. Groove 182 has a leading side wall 186, a trailing side wall 184, and a bottom wall 188. The outer end of the coupling seal includes an upper, contacting or sealing portion 192 for contacting the respective end surface 27a or 29a of the cavity 22, and a lower, relieved portion 194. The relieved portion 194 is inclined away from the contact portion 192 toward the opposite, inner end of the cylindrical body 180 so that it never comes into frictional contact with an end wall surface of the cavity 22. Slots 190 are formed in the cylindrical body 180 on opposite sides of the groove 182 and communicate with the end wall surface 192 at the periphery thereof for receiving the ends of the side sealing strips 116. A seal blade pressure member comprising an integral extension arm 196 is formed on the cylindrical body with an outer end surface that is coextensive with the outer end surface 192. The extension arm is received in a cutaway portion 145 (FIG. 22) of the retaining member when the cylindrical body 180 is received in the recess 142, and has an outer, inclined surface 196a that forms a continuation of the surface 154 of the retaining member.

As shown in FIGS. 14 and 20, the side wall 186 is convex, and the side wall 184 has an upper portion 185 which extends at a slight angle from the lower portion 187. The lower portion 187 is complementary to the lower portion 176 of the trailing side surface of the apex seal blade. A seal blade contacting member or projection 195 is formed on the upper portion of the extension arm 196, the projection 195 having a curved surface such that it engages one of the cam surfaces 178 on the seal blade along a line or substantial point contact, the approximate position of the substantial point contact being indicated by reference numeral 197.

As shown in FIG. 14, a clearance is always maintained between the side walls of the groove 182 and the respective opposed side surfaces of the seal blade so that the coupling seal contacts the seal blade only at point 197. That is to say, the only portion of the coupling seal member 122 that contacts the seal blade 124 is the seal blade contacting member 195.

With reference to FIG. 13, the seal blade spring 126 is received in the groove 134 and has a central portion that rests on the bottom wall 140 of the groove. Extending upwardly (as viewed in FIG. 13) from opposite ends of the central portion is a pair of curved spring arms 126a, and the seal blade is seated in the groove and rests on the spring arms 126a, the curvature of the spring arms 126a conforming to the curvature of the junction between the bottom surface 164 and the projections 166 on the seal blade. The spring 126 thus biases the seal blade to project from the groove 134.

The coupling seal springs 128 are in the form of looped spring washers that are inserted into the coupling seal recesses 142 against the end walls 144 thereof for biasing the coupling seals outwardly of the recesses 142. The coupling seal spring and coupling seal member may also be constructed to coact with each other in such a manner that the coupling seal member 122 is biased by the coupling seal spring to rotate in the direction of arrow 52 in FIG. 14 to further maintain the substantial line contact engagement at 197. The spring arms 126a of the apex seal spring 126 project through and are surrounded by the coupling seal springs 128. The coupling seals 122 are then inserted into the recesses 142 with the extension arms 196 received in the respective recesses 145 of the retaining member (FIG. 11). Springs 128 bias the coupling seals 122 to project outwardly from the recesses 142 such that the contact portions 192 engage the respective end wall surfaces 27a and 29a of the cavity 22 indicated in phantom lines in FIG. 13. As shown in FIG. 10, for example, a force in the direction of arrow 52a is applied to the cam surface 178 by the frictional contact on surface 192 and any spring force tending to rotate the coupling seal in the direction of arrow 52.

The contacting member 195 on the extension arms 196 engage the seal blade 124 at the cam surfaces 178 and apply pressure along the contact line 197. Any force tending to urge the projection 195 toward the left in FIGS. 10 and 14 produces a reaction component of force urging the coupling seal to extend further axially outwardly of the recess 142 in a direction away from the end wall 144 thereof and toward the respective surfaces 27a and 29a. For example, the coupling seal 122 in FIG. 11 is cammed toward the left by the engagement of projection 195 on the extension arm 196 with the cam surface 178 on the seal blade 124. Further-

more, the engagement of the contact members 195 with the cam surfaces 178 at the opposite ends of the seal blade tends to maintain the seal blade 124 in a centered position in which both of its end surfaces 158 are out of frictional engagement with the end wall surfaces 27a and 29a so that there is a minimum of frictional retarding of radial movement of the seal blade 124 caused by frictional engagement between the seal blade 124 and surfaces 27a and 29a. Additionally, the cam surfaces 178 are inclined downwardly and inwardly such that pressure between the seal blade contact members 195 and the cam surfaces 178 produces reaction components of force urging the seal blade radially outwardly of the groove to increase the pressure between the tip of the seal blade and the trochoid surface.

The trailing side surface of the seal blade engages the trailing side wall of the groove 134 with substantially a line contact indicated at 198 in FIGS. 14, 14A, 14B and 21. Any forces tending to urge the apex seal blade toward the left in FIGS. 14 and 14A, causes a reaction component of force between the surfaces 148 and 174 which tends to urge the apex seal blade to extend radially outwardly (in the direction of the arrow 198a) of the groove. Furthermore, with the seal blade 124 having a hardness different from the retaining member, the surfaces 148 and 174 will wear, due to the tilting of the seal blade 124, and will burnish and conform to each other and thereby maintain the tip of the seal blade in contact with the trochoid surface to compensate for irregularities in the trochoid surface, and will also maintain a seal along the conformed configuration above and below the theoretical line contact 198.

The wear pattern defining the conformed configuration on the seal blade is illustrated in the shaded area 174a in FIG. 21. The wear pattern defining the conformed configuration on the surface 148 of the apex seal groove of the retaining member is illustrated by the phantom lines 148a and 148b in FIG. 22.

With the retaining member 134 installed separately onto the rotor, the retaining member can be of a material that can best meet the requirements for sealing cooperation with the apex seal blade, which requirements are not necessarily the same as the requirements of the material of the rotor. For example, the material of the rotor may have to have certain properties of strength and hardness for its function, while the sealing requirements would be better served if the apex seal blade were received in a groove of a member having properties, metallurgical or otherwise, different from the rotor; i.e., the apex seal blade might very well function better seated in a member of softer and/or tougher material than required for the rotor so that the seal blade will better seal by conforming and seating onto the cooperating surfaces of the apex seal groove. The use of a separate retaining member for the apex seal blade thus increases the flexibility of the design of the rotor assembly in that it makes it possible for the rotor to be manufactured of material having the optimum properties for the rotor function, which properties might otherwise not be best suited for the sealing function.

It is also within the scope of this invention to (instead of providing a retaining member to be installed separately onto the rotor) form the apex seal groove directly into the rotor and plate, coat, or bond onto the surfaces of the groove, a material that will better cooperate with the apex seal blade for its sealing function. For example, the cooperating side wall surfaces of the

groove or seal blade can be plated or coated with a material softer than the material of the rotor so that the blade and side walls of the groove will better conform to each other, to assure proper seating of the blade against the cooperating side walls of the groove.

The retaining member thus may be made of material having strength, density, malleability, yieldability, high lubricity, elongation and other properties different from the material of the rotor so as to provide optimum sealing cooperation with the seal blade. The same is true of the material that can be applied by coating, plating, bonding, etc. to the surface of an apex seal groove formed directly into the rotor material.

The material of the side walls of the groove against which the seal blade seats should have high lubricity, or low friction characteristics, to minimize the resistance to movement of the seal blade relative to the groove and other cooperating members.

Again referring to FIG. 14, rotation of the rotor in the direction of arrow 148 produces friction forces in the opposite direction on the surfaces in contact with the end wall surfaces 27a and 29a as well as on the working surface of the tip portion 168 of the blade. Since the lower portion 194 of the coupling seal outer end is not in contact with the associated end wall surfaces 27a or 29a, and since the entire outer surface of the extension arm 196 together with the upper portion 192 of the coupling seal is in contact with the associated end wall surfaces 27a and 29a, a substantial rotary force in the direction of arrow 52, opposite to the direction of rotation of the rotor, is imposed on the coupling seal 122. This is because the speed of the surface of the coupling seal in frictional contact with the end wall surfaces increases along the length of the radius R of the rotor 110 so that the frictional forces near the upper end of the contact arm 196 as viewed in FIG. 14 are greater than the frictional forces on the lower periphery of surface 192 near the bottom wall 140 of the groove 182.

Since the friction forces on the coupling seal tends to produce a counterclockwise rotation of the coupling seal, the contact member 195 on the extension arm 196 is urged by the friction forces into engagement with the cam surface 178 with a force that increases with the friction forces on the coupling seal. The increased force urging the contact member 195 into engagement with the cam surface 178 produces, by the reaction between the cam surface 178 and the contact member 195, an increased force tending to urge the coupling seal outwardly into engagement with its respective end wall surface 27a or 29a. Furthermore, a counterclockwise rotational force is induced onto the seal blade 124 by the intermittent contact of the upper portion 158 of the end surface of the seal blade since the lower portion 159 is relieved and does not come into contact with the end wall surfaces 27a or 29a under any circumstances.

The counterclockwise rotational force on the coupling seal also increases the pressure between the surfaces 174 and 148 of the seal blade and side wall of the groove 140 at the contact line 198. The increased pressure increases the reaction component of force tending to cause the seal blade to move radially outwardly toward engagement with the trochoid surface 24. Furthermore, the forces imposed on the seal blade by the coupling seals tend to rotate the seal blade in a counterclockwise direction as viewed in FIGS. 14 and 14A such that the lower, right-hand portion of the leading

surface 160 engages the side wall 136 at 199. Thus, as viewed in FIG. 14A, the seal blade 124 has a line contact with the trailing side wall 138 of the groove 134 at 198 and a contact with the leading side wall 136 of the groove at 199. The contact forces between the end surfaces of the coupling seal and the end wall surfaces 27a and 29a, and between the coupling seal and the seal blade 124, instead of adversely affecting the sealing force of the seal blade as in the prior art conventional construction described previously, produce reaction forces that urge the seal blade in a sealing direction to enhance the sealing force of the sealing blade. The friction forces on the end surfaces of the coupling seal increase the force at the contact line 198, which, because of the configuration of the surfaces 148 and 174, increases the component of force tending to urge the seal blade to extend radially outwardly from the groove 134. The friction forces on the coupling seals, because of the engagement between the extension arm 196 and the cam surfaces 178, also tend to keep the end surfaces 158 of the seal blades out of engagement with the end wall surfaces 27a and 29a which would produce friction forces tending to retard movement of the seal blade along the radius R of the rotor.

As shown in FIG. 14, the point of contact 197 is spaced vertically above the line of contact 198 by a distance j . Consequently, the blade is urged by the forces at point 197 and line 198 to tilt in a counterclockwise direction as viewed in FIG. 14 to establish the contact engagement at 199 (FIG. 14A) between the leading side wall 136 of the groove 134 and the leading side surface 160 of the seal blade and relieve the frictional contact between surfaces 150 and 176. The contact at 199 is located near the lower edge of the side surface 160 as viewed in FIG. 14A.

Again referring to FIG. 14, a clearance x is provided between the surfaces of the ends of the side seal strip 116 and each surface of the slots 146 of the retaining member 120, as well as between the coextensive slots 190 of the coupling seal 122. The clearance x between the coupling seal and the side seal strip 116 is sufficient so that any rotation of the coupling seal due to the frictional forces acting on the coupling seal is insufficient to bring the coupling seal into direct contact with the side seal blade. Since the retaining member 120 does not move relative to the rotor, the surfaces of the slot 146 are never in contact with the side seal strip 116. Consequently, movement of the side seal strip 116 in the direction of the rotary axis of the rotor is never inhibited by the coupling seal, or by the retaining member. Thus, the apex seal assembly 119 not only is constructed to minimize adverse conditions on the apex seal, but also eliminates an adverse condition acting on the side seal strips as would occur in the prior art construction described above. The clearance x , while sufficient to prevent frictional engagement between the side seal strips and the surfaces of the slots or notches 146 and 190, is not sufficient to permit significant leakage around the side seal strip since any leakage must pass through a relatively narrow space, and the configuration of the space around the end of the strip provides a baffling effect to retard the flow of fluid.

Again referring to FIG. 14, the working surface of the tip 168 of the seal blade is defined between an angle b , and is divided between a leading portion 170 and a trailing portion 172. The leading portion 170 is located on the right-hand side (as viewed in FIG. 14) of an

imaginary rake angle line that intersects the tip 168, and which imaginary rake angle in FIG. 14 is coextensive with the radial line R. The leading portion 170 engages the trochoid surface 24 when the seal blade 124 is in a negative rake position with respect to the trochoid surface. The trailing portion 172 is located on the left side of the imaginary rake angle line as viewed in FIG. 14 and engages the trochoid surface 24 when the seal blade 124 is in a positive rake position with respect to the trochoid surface. When the seal blade is in a zero rake position with respect to the trochoid surface 24 (such as is shown in FIG. 17), the imaginary rake angle line is disposed perpendicular to the trochoid surface 24, and the tip 169 contacts the trochoid surface at the point of intersection between the tip 168 and the rake angle line.

As shown in FIG. 14, the leading portion 170 of the working surface of the tip 168 has a radius of curvature R4, the center 173 of which is located substantially on the imaginary rake angle line, or radial line R in FIG. 14. The trailing portion 172 of the working surface of the tip 168 has a radius of curvature R5, the center 171 of which is located on the leading side of the imaginary rake angle line R in FIG. 14, and is spaced below the center of curvature 173 of the leading portion 170. The radius R5 is larger than the radius R4; hence the angle b_1 is greater than the angle b_2 , and the expanse of the trailing portion 172 is greater than the expanse of the leading portion 170. Consequently, as pointed out in greater detail below, the point of contact between the trailing portion 172 of the working surface of the tip 168 tends to move outwardly relative to the groove 134 and to the axis 31 of the rotor as the rake angle increases in the positive rake angle direction.

FIG. 14B illustrates the manner in which the configuration of the trailing portion (or heel portion) 172 of the working surface of the tip 168 compensates for distortions in the trochoid surface so that the seal blade tip 168 will remain in sealing engagement with the trochoid surface. In the left-hand illustration of FIG. 14B, a conventional seal blade 40' of the type shown in FIGS. 1 and 6A-6E is illustrated in approximately zone J (FIG. 3), and in the right-hand illustration of FIG. 14B, the seal blade 124 is illustrated in the same position with respect to the trochoid surface as the seal blade 40'. Both the leading and trailing portions of the tip portion of the seal blade 40' has a radius of curvature R8.

The theoretically perfect position of the trochoid surface is indicated in phantom lines by reference numeral 24. The actual position of the trochoid surface in approximately zone J (FIG. 3) is indicated by reference numeral 24'. The actual position of the trochoid surface 24' is separated from the theoretical position 24 by a distance g' due to manufacturing tolerances and wear and distortion caused by stress and heat.

The trailing or heel portion 172 of the seal blade 124 in FIG. 14B advances outwardly in the direction of the trochoid surface 24' as the tip of the seal blade 124 rotates clockwise in FIG. 14B about the center 173 in a positive rake condition of the seal blade. As a consequence, there is a compensation for the distance or space g' between the theoretical position of the trochoid surface 24 and the actual position of the trochoid surface 24', which causes the blade tip contact point p to remain in engagement with the trochoid surface. The trailing portion 172 thus advances outwardly to com-

pense for the distortion distance g' . On the other hand, the tip of the prior art blade 40' tends to separate from the trochoid surface because the contact point p' tends to remain located at the theoretical surface 24.

As pointed out previously, the point of contact 197 in FIG. 14 between the projection 195 and cam surface 178 is spaced vertically above the line of contact 198 on the trailing side of the seal blade by a distance j . The vertical spacing between the point of contact 197 and line of contact 198 produces a counterclockwise moment as viewed in FIG. 14 that urges the lower portion of the leading side of the blade into contact with the leading side wall 136 of the groove at the substantial line contact 199 (FIG. 14A). As pointed out previously, the counterclockwise rotation of the coupling seal member 122 increases with the speed of the rotor so that the pressure at the point of contact 197 increases with the speed of the rotor. The force between the projection 195 and cam surface 178 in the illustrated embodiment along the point of contact 197 is thus generated by the frictional engagement between the surface 192 of the coupling seal member 122 and its associated end wall surface 27a or 29a; however, the force at the point of contact 197 may also be provided by a spring or the like. Increased pressure between the projection 195 and cam surface 178 increases the pressure at the line of contact 198 which tends to cause the seal blade 124 to move upwardly in FIG. 14 because of the configuration of the contacting surfaces 174 and 148 along the line 198. Thus, the seal blade is held in contact with the trailing or drive side wall surface 148 at each position of the seal blade along the trochoid surface 24. During its travel along the trochoid surface, the seal blade 124 tends to slide along and/or rock around the convex ramp surface 148 in response to the friction forces acting on the seal members, which friction forces always produce components of force tending to urge the seal blade 24 upwardly in FIG. 14. Thus, the friction forces between the tip of the seal blade 122 and the trochoid surface 24, together with the friction forces between the surface 192 of the coupling seal 122 and any friction forces caused by intermittent contact between surface 158 of the end of the seal blade produce, because of the configuration of the components of the seal assembly, reaction force components that: (1) urge the seal blade radially outwardly of the groove because of the contact between projection 195 and cam surface 178 at the contact point 197, (2) tend to maintain the seal blade in a centered position with respect to the end wall surfaces 27a and 29a because of the contact between projections 195 and the cam surfaces 178, (3) tend to maintain a contact at 199 (FIG. 14A) between the leading side surface 160 of the seal blade and the leading side wall 136 of the groove, (4) tend to maintain the trailing side surface 174 of the seal blade in contact with the trailing side wall of the groove with a substantial line contact at 198, and (5) urge the apex seal blade to rock around the substantial line of contact 198 and slide upwardly around the convex surface 148 to maintain the tip of the seal blade in contact with the trochoid surface 24. Any gas pressure in the groove acts against the trailing side surface 176 to further increase counterclockwise tilting of the blade in the groove to maintain contact of the blade at 198 and 199. Consequently, the frictional forces that would

normally be adverse to the sealing function of the blade are harnessed to produce components of force that enhance the sealing function of the seal blade.

FIGS. 15 through 19 illustrate the apex seal of FIGS. 10 and 14 as it moves from the left-hand firing position to the right-hand firing position along the trochoid surface 24. In FIGS. 15 through 19, the surfaces in contact with the end wall surfaces 27a or 29a are shaded, these surfaces including the side seal strips 116 and surface 192 of the end of the coupling seal 122. The upper portion 158 of the end surface of the apex seal blade 124 is also shaded because, as pointed out above, it may be in intermittent contact with the end wall surfaces 27a or 29a. In all positions of the seal assembly 119, the seal blade pressure member or extension arm 196 holds the trailing surface 174 of the seal blade against the trailing side wall 138 of groove 182, regardless of the pressure conditions in the chambers on the opposite sides of the seal blade.

In the left-hand firing position of FIG. 15, the contact point p between the trochoid surface 24 and the tip portion of the seal blade 124 is on the leading portion 170 of the working surface and is located at an angle w to the right of the rotor radius R . As the apex seal assembly moves from the left-hand firing position in FIG. 15 toward the lobe 28 through quadrant E (FIG. 3), the blade tip rotates approximately about the point 173 (FIG. 14) since the rake angle of the blade is negative in quadrant E, and the point p moves along the leading portion 170 of the working surface. The pressure on the right-hand side of the blade in the ignition and expansion chamber 42 is greater than the pressure on the left-hand side of the blade. The frictional forces on surface 192 of the coupling seal tending to rotate the coupling seal in the counterclockwise direction of arrow 152 also maintain the seal blade in contact with the side walls of the groove along the contact lines 198 and 199 (FIGS. 14A and 21).

FIG. 17 illustrates the seal blade at the neutral position at lobe 28, and FIG. 18 illustrates the seal as it moves into quadrant F past the lobe 28. In FIG. 18, the contact point p has moved to the trailing portion 172 of the working surface of the blade and the rake angle has changed to positive. However, the component of force tending to urge the seal blade inwardly along the radius R out of contact with the trochoid surface 24 is resisted by the configuration of the contacting surfaces 148 and 174 (FIG. 14A) so that the blade tends to stay in contact with the trochoid surface 24 and prevent the leakage condition illustrated in FIGS. 6A-6E. Furthermore, as pointed out previously, the configuration of the trailing portion of the tip is such that the tip contact point advances to correct for any error in the position of the trochoid surface from the theoretically perfect position.

FIG. 19 illustrates the seal assembly in the right-hand firing position, and although the high pressure condition has shifted to the left-hand side of the assembly as viewed in FIG. 19, the coupling seal still urges the blade into contact with the trailing side wall of the groove 134 so that the blade is continuously urged radially outwardly toward the surface 24 by the contacting surfaces 174 and 148.

The configuration of the tip 168 of the seal blade assists the tip of the blade to follow any distortions in the trochoid surface 24 caused by temperature expansion, distortion and manufacturing errors. This is particularly critical in zone J (FIG. 3) because, in addition to the adverse conditions in zone J previously discussed, the lobes 26 and 28 tend to move toward and away from each other each time ignition and explosion takes place because of the sudden rise in pressures and temperature upon explosion of the fuel. The movement of the lobe 28 from its true position of the trochoidal form caused by the temperature and pressure expansion, encourages the adverse tendency of the tip of the seal blade to skip into and out of engagement with the trochoid surface 24 as it moves into zones J from a negative to positive rake angle. The configuration of the trailing portion 172 of the working surface of the tip of the blade is such that some point along the surface 172 always tends to move toward the trochoid surface 24 as the blade moves through a positive rake zone. Therefore, any tendency of the trochoid surface to fall away from the working surface of the seal blade in a positive rake zone is compensated for by the configuration of the trailing portion 172 of the working surface of the blade tip serves to assure that contact will be maintained between the blade tip and the trochoid surface 24 despite temperature expansion distortions and manufacturing tolerances in all positions of the blade in a positive rake zone.

The extent of the positive rake zones can be reduced by tilting the apex seal blade and its groove in the negative rake direction with respect to the imaginary rake angle lines that are coextensive with radial lines through the axis 31 of the rotor.

FIGS. 23 through 26 illustrate a modification of the construction shown in FIGS. 9-22 wherein an apex seal assembly designated collectively by reference numeral 200 includes a retaining member 202, a coupling seal 204, and an apex seal blade 206. The retaining member 202 is formed with an elongated groove 208 for receiving the apex seal blade, and a pair of recesses 209 at the opposite ends of the groove 208 for receiving the coupling seals 204. Groove 208 includes a trailing side wall 210, a leading side wall 212 and a bottom wall 214. The trailing side wall 210 is convex and the leading side wall 212 is concave.

The seal blade 206 is received in the groove 208 and has a leading side surface 216 which is convex and which conforms to the curvature of the side wall 212, and a trailing side surface 218 which is concave and which conforms to the curvature of the side wall 210. The seal blade 206 is seated on a spring, which, in the drawing, is identical in construction to spring 126 illustrated in FIG. 13. The outer tip portion of the seal blade 206 in the illustrated embodiment of FIGS. 23 through 26 is identical in configuration to the tip portion 168 of the seal blade 124 of the previously described embodiment. Conventional coupling seal springs 224 are received in the recesses 209 for biasing the coupling seals 204 into engagement with the end wall surfaces of the engine cavity.

The seal blade 206 is formed on its trailing side with a recess 220 for trapping gas pressure to serve as a pressure pad to tend to reduce the frictional contact between the surfaces 210 and 218 and substantially elimi-

nate frictional drag between surfaces 210 and 218. Cam surfaces 226 are formed on the leading side surface of the seal blade 206, the cam surfaces being inclined in the same direction as the cam surfaces 178 of the previously described embodiment; that is, the cam surfaces 226 each have end edges 226a and 226b, and the surface 226 is inclined inwardly from the end edge 226a to the end edge 226b such that the end edge 226b defines a shoulder with the side surface 216, and such that the width of the seal blade at the end edge 226b is less than the width of the seal blade at end edge 226a.

Each coupling seal 204 has a cylindrical body 228 formed with a groove 230 having side walls that conform substantially to the configuration of the side walls of the groove 208. Formed on the leading side wall of the groove 230 is a seal blade pressure member comprising a projection 232 (FIG. 25) which engages one of the cam surfaces 226 on the apex seal blade 206. Any forces tending to rotate the coupling seal 204 in FIG. 25 in a counterclockwise direction to urge the projection 232 into contact with the cam surface 226, and the contrast between the projection 232 and cam surface 226 produces a reaction force having a component tending to urge the coupling seal 204 outwardly into engagement with the end wall surface 27a of the trochoid cavity and at the same time tending to urge the seal blade 206 toward a centered position with respect to the end wall surfaces 27a and 29a.

The friction forces on the end surface of the coupling seal member 204 produces a counterclockwise rotation in the direction of arrow 52 when the rotor is rotating in the direction of arrow 48, which counterclockwise rotation urges the seal blade 206 into the trailing side wall 210 of the groove 208. The curvatures of the contacting surfaces 210 and 218 are such as to urge the seal blade 206 to project radially outwardly from the groove 208. Furthermore, the curvatures of the contacting surfaces 210 and 218 resist any forces tending to push the seal blade inwardly along the radius R of the rotor and out of contact with the trochoid surface 24.

As in the previously described embodiment of FIGS. 9-22, the coupling seal member 204 contacts the seal blade 206 only at the contact member 232. A clearance is provided between all other portions and surfaces of the coupling seal member 204 and the seal blade 206.

As shown in FIG. 23, the retaining member 202 is formed with slots 234 for receiving the ends of the side seal strips 116, the slots 234 being provided with a clearance so that the side seal strips are never in contact with the surfaces of the slots. Moreover, the ends of the side seal strips 116 are never in contact with the surface of the coupling seal 204 so that the counterclockwise rotational movement necessary to maintain the apex seal in contact with the trailing side wall 210 of the groove 208 is not retarded by any frictional engagement between the side seals and the coupling seal. Since the apex seal blade is urged toward the trailing side wall 210 of the groove 208, pressure will tend to leak past the leading side surface 216 of the apex seal and become trapped in the recess 220. The pressure in the recess 220 will reduce the pressure between the contacting surfaces 210 and 218 to thereby reduce the frictional drag tending to resist movement of the seal blade along the radius R of the rotor.

In both the embodiments of FIGS. 10 through 22 and 23 through 26, the use of the retainers 120 and 202, re-

spectively, facilitates the manufacture of the rotors, particularly in connection with the forming of the grooves of the side seal 116. A problem with cutting the grooves for the side seal 116 in the prior art rotors is to cause the cutting tool to enter and exit from the groove within the close dimensional tolerances that would be required if the groove extended to the coupling seal recess, assuming the coupling seal recess is to be formed directly into the rotor. By housing the apex seal assembly in the separate retainer such as the retaining members 120 or 202, the ends of the grooves for the side seals 116 at each apex portion are spaced further apart to reduce the problems of abruptly changing the direction of the cutting operation.

In both the embodiments of FIGS. 10 through 22 and 23 through 26, the various components of each of the sealing assemblies have cooperating surfaces that tend to maximize the freedom of movement of the seal blade along the radius R of the rotor, in addition to producing reaction components of force that urge the seal blade in a sealing direction in response to forces that are generally considered to be undesirable. Furthermore, in both of the embodiments of FIGS. 10 through 22 and 23 through 26, the coupling seal members have maximum freedom of movement along their longitudinal axes, that is, along axes parallel to the axis of rotation of the rotor because the frictional engagement with the side seals is eliminated, and because the engagement between the coupling seals and apex seal blade produces reaction components of force that urge the coupling seal members to project outwardly into sealing engagement with the surfaces 27a and 27b.

Thus, in the embodiment of FIGS. 10 through 22, a rotary engine or the like is provided with a sealing assembly 119 for providing a sliding seal between the two relatively movable members of the rotary engine, the sealing assembly comprising a groove 134 formed in one of the relatively movable members 110, the groove 134 extending substantially transversely of the direction of relative movement between the relatively movable members 110 and 24, the groove 134 having a leading side wall 136, a trailing side wall 138, and a bottom wall 140 extending between the side walls. A seal blade 124 is received in the groove 134, the seal blade 124 having a tip portion 168 with a working surface 170, 172 defined thereon for sliding, sealing engagement with the surface 24 of the other of the relatively movable members. The seal blade 124 has a trailing side surface 174 extending from the trailing edge of the outer tip portion 168 and disposed in opposed relationship to the trailing side wall 138 of the groove 134. The blade 124 has a leading side surface 160 that extends from the leading edge of the outer tip portion 168 and is disposed in opposed relationship to the leading side wall 136 of the groove. Cooperating cam surfaces 148, 198 are provided on the trailing side wall of the groove and the trailing side surface of the blade which are operable in response to forces urging the trailing side surface into contact with the trailing side wall to produce reaction force components urging the outer tip portion of the blade to extend from the groove.

In the embodiment of FIGS. 23 through 26, the sealing assembly comprises a groove 208 formed in one of the relatively movable members and extending transversely of the direction of relative movement between the relatively movable members 110 and 24. The groove has a leading side wall 212, a trailing side wall

210, and a bottom wall 214. A seal blade 206 is received in the groove, the seal blade having a tip portion identical to the tip portion of the seal blade 124. The seal blade 206 has a trailing side surface 218 extending from the trailing edge of the tip portion and disposed in opposed relationship to the trailing side wall 210, and a leading side surface 216 extending from the leading edge of the tip portion and disposed in opposed relationship to the leading side wall 212 of the groove. Cooperating cam surfaces 210 and 218 are formed on the trailing side wall of the groove and trailing side surface of the blade which are operable in response to forces urging the trailing side surface into contact with the trailing side wall to produce reaction force components urging the outer tip portion of the blade 206 to extend from the groove 208.

As pointed out previously, the peak forces that are instantaneously applied to the seal blades at the leading and trailing ends of the ignition chamber upon explosion of the fuel produce undesirable conditions that increase wear on the seal blade and increase the tendency of the seal blade to separate from the trochoid surface and permit leakage. The impact forces introduced by intermittent high pressures of the engine illustrated graphically at points 88a and 88d in FIG. 2 far exceed the necessary force on the apex seal to maintain adequate sealing between the tip of the seal blade and the trochoid surface 24. Furthermore, the impact forces decrease the life of the trochoid surface 24 and cause extending yield and irregularities in the surface 24 which further aggravates and encourages the tendency of the seal blade to skip into and out of engagement with the trochoid surface 24. The adverse conditions caused by temperature and pressure expansion, as discussed above, are thus further aggravated by the results of the high impact forces between the apex seal blades at the leading and trailing ends of the ignition chamber upon ignition and explosion of the fuel. As a result, the peak sealing pressure, which is excessive, is reduced, and the low sealing pressure is increased so that the pressure conditions illustrated by curve 90 in FIG. 2 are more closely approached.

FIGS. 27 through 42 illustrate a rotor construction utilizing the apex seal assembly of FIGS. 10 through 22 in which provision is made for reducing the impact forces on the apex seal blades caused by ignition. In FIG. 27, as in FIG. 1, the rotor is in the firing position, and the cavity 22 is divided into an ignition and expansion chamber 42, an exhaust chamber 44, and an intake and compression chamber 46. The three apex seal assemblies are individually indicated by the reference characters I, II and III. The apex seal assembly I is connected on its leading side with a passage 236 and on its trailing side with a passage 238. The apex seal assembly II is connected on its leading side with passage 238 and on its trailing side with a passage 240. The apex seal assembly III is connected on its leading side with passage 240 and on its trailing side with passage 236. As shown in FIGS. 14A and 21, passages 235 may be formed in the apex seal blade 124 with an opening in the tip portion on the trailing side of the trailing portion 172 outside of the working portion of the tip of the blade so that the tip opening of the passage never contacts the trochoid surface 24. Passages 235 communicate with the passage 235a in the retaining member 120 through one or more ports 235c, passage 235a communicating at one end with the groove 134 through the trailing side

wall 138 of the groove. The leading side wall 136 of the groove 134 communicates with one end of each of the passages 235b formed in the retaining member 120. The passages 235, 235a and 235c will each communicate with one only of the passages 236, 238 or 240 shown in FIG. 27. Fluid pressure through passage 235 exerts pressure both against the bottom surface 164 of the seal blade and against surface 176 on the trailing side surface. The pressure on surface 176 urges the leading surface of the seal blade to maintain the substantial line contact at 199 with the leading side wall of the groove 134. The pressure acting on the bottom surface 164 urges the seal blade radially outwardly of the groove toward the trochoid surface.

In FIG. 27, the apex seal assembly I is in the left-hand firing position and constitutes the trailing seal of the ignition chamber 42, the apex seal assembly II is in the right-hand firing position and constitutes the leading seal of the ignition chamber 42, and the apex seal assembly III is in the neutral position at the lobe 26. Upon ignition, the high pressure from chamber 42 flows past the leading side of the trailing apex seal blade 124 in position I into passage 236 and is discharged on the trailing side of the apex seal in position III, or into the exhaust chamber 44. The trailing side of the apex seal blade 124 in position I is connected through passage 238 with the leading side of the seal blade 124 in position II—the right-hand firing position. The leading side of the seal blade in the right-hand firing position II is connected with the exhaust chamber so that there is little or no pressure exerted through passage 238 on the seal blades in positions I or II. A portion of the pressure upon ignition in the firing chamber will be dissipated through ports 236 and 240 to reduce the impact pressure urging the seal blades 124 at positions I and II radially outwardly into contact with the trochoid surface 24 and thus reduce the frictional forces on the working surface of the seal blades. The loss in pressure, will not, however, be sufficient to significantly reduce the power of the engine but will improve the sealing function of the seal blades 124 in that the friction forces on the working surface of the seal blades will be reduced which, as pointed out above, is particularly critical as the blade moves across the lobe 28 into the positive rake quadrant F. The size of the passages 236, 238 and 240 are of predetermined dimension to prevent an excessive loss of pressure in the ignition and expansion chamber 42, but are large enough to reduce the impact pressure on the seal blades at positions I and II.

As shown most clearly in FIG. 28, the seal assembly at position I in the left-hand firing position has relatively high pressure on its right-hand, leading side in chamber 42 from ignition and explosion of the fuel in chamber 42, and relatively low pressure on its left-hand side in the intake and compression chamber 46. In the firing position, the pressure in chamber 46 is at its lowest, and ignition and explosion of the gases in chamber 42 causes a sudden increase in the pressure in chamber 42 which is at its peak upon explosion of the fuel in the firing position shown in FIG. 27. The high pressure gases in chamber 42 upon ignition and explosion of the gases flow into the space between the leading side surface of the apex seal blade 124 in position I (FIG. 28) and the leading side wall of the groove 134 into the accumulator passage 236. While a portion of the high pressure gases from chamber 42 may leak into groove 134 beneath the bottom wall surface 164 of the seal

blade 124, the amount of pressure will be controllably reduced because of the exposure of the chamber 42 to the accumulator passage 236. Consequently, the impact force of the fuel explosion acting on the bottom surface 164 of the apex seal blade 124 will be substantially reduced, both by virtue of a bleeding off of some of the instantaneous pressure rise into the accumulator passage 236, and by the bleeding off of pressure beneath the apex seal blade 124 in groove 134 through the passages 234 in the apex seal blade. Moreover, the high pressure acting on the leading side surface of the apex seal blade 124 in position I of FIG. 28 will tend to increase the pressure at the substantial line contact points 198 and 199 to reduce the likelihood or amount of leakage from chamber 42 past the substantial line of contact 199. The portion of the high pressure gases at explosion from chamber 42 that flows into the accumulator passage 236 will flow to the trailing side of the seal blade 124 at position III (FIG. 30). The accumulator passage 238 on the trailing side of the seal blade 124 at position I is connected with the leading side of the seal blade 124 at position II (FIG. 29).

With reference to FIG. 29, the seal blade 124 at position II is in the right-hand firing position and the opening in the tip of the blade or passage 234 is exposed to the pressure in the ignition chamber 42. The seal blade 124 in position II has a relatively high pressure condition in chamber 42 upon ignition and explosion on its left-hand side and has a low pressure condition on its right-hand side in the exhaust chamber 44. The exhaust chamber 44 is in a position of low pressure since it is exposed to the exhaust port 25. Consequently, the accumulator passage 238 is exposed at each end to the low pressure conditions in the exhaust chamber 44 and intake chamber 46 when the rotor is in the firing position illustrated in FIG. 27.

Still referring to FIG. 29, upon ignition and explosion of the gases in chamber 42, a portion of the high pressure at ignition and explosion of the gases is bled off from chamber 42 through passage 234 to the accumulator passage 240. The high pressure gases also flow through passage 234 into the groove 134 and into the space between the trailing side surface of the apex seal blade 124 and the trailing side wall of the groove 134. The pressure between the trailing side surface of the apex seal blade 124 and the trailing side wall of the groove 134 in position II in FIG. 9 will exert a pressure toward the right as indicated by arrows 72y to increase the pressure at the substantial line of contact 199 between the leading side surface of the seal blade 124 and the leading side wall of the groove 134 to decrease the likelihood of any leakage of high pressure gases from chamber 42 past the substantial line of contact 199 on the leading side of the seal blade 124. Again, however, the bleeding off of a portion of the instantaneous pressure rise in chamber 42 through passages 234 into the accumulator passage 240 will reduce the impact pressure on the seal blade 124 exerted against the bottom surface 164 thereof and, hence, the condition illustrated at point 90d on curve 90 of FIG. 2 will be more closely approximated, thus reducing the distortion of the trochoidal surface 24. The high pressure gases bled into the accumulator passages 240 in the firing position of FIG. 27 flow to the leading side of the apex seal blade 124 in position III.

With reference to FIG. 30, the outlet end of the accumulator passage 240 is exposed to the space between

the leading side surface of the apex seal blade 124 in position III, and the discharge end of the accumulator passage 236 is exposed to the passage 234 of the apex seal blade 124 and hence communicates with the exhaust chamber. However, the diameters of the accumulator passages 236 and 240 are small enough so that there is a substantial pressure drop between the inlet ends of passages 236 and 240 at positions I and II, respectively, and their discharge ends at position III. Therefore, even though the accumulator passages 236 and 240 serve to dampen the impact pressure on the bottom surfaces 164 of the apex seal blades 124 in positions I and II upon ignition and explosion of the gases in the firing position of the rotor, the amount of pressure bled into the intake and exhaust chambers through passages 240 and 236, respectively, past the apex seal blade 124 in position III, is not sufficient to adversely effect the intake and exhaust phases of the engine. Furthermore, the apex seal blade 124 at position III in FIG. 30 acts in the manner of a reed valve by virtue of the pressures from passages 236 and 240 simultaneously acting on its trailing and leading surfaces, respectively, which will further cause a pressure drop between the discharge ends of the accumulator passages 236 and 240 and the exhaust and intake chambers 44 and 46, respectively. Moreover, it is believed that any increase in temperature caused by gases flowing from the accumulator passage 240 into the intake chamber 46 will actually tend to increase the efficiency of the engine since ignition and explosion occur more efficiently when the gases at compression are at a higher temperature.

The reduced impact loading on the trailing and leading seal blades 124 at positions I and II at ignition and explosion of the gases increases the life of the seal blades 124 as well as the trochoid surface 24 since the fatiguing conditions on the trochoid surface at the firing position of the rotor are substantially improved by the reduction of the impact forces between the seal blades and the trochoid surface.

FIG. 31 illustrates the rotor as it has moved past the ignition position of FIG. 27. Chamber 42 is in an expansion phase, chamber 44 is still in an exhaust phase, and chamber 46 is at the end of intake phase just prior to the compression phase.

With reference to FIG. 32, the seal blade 124 in position I still has relatively high pressure on its right-hand side in the expansion chamber 42 and relatively low pressure on its left-hand side from the intake and compression chamber 46. While the pressure is reducing in chamber 42 during the expansion phase, it is still at a relatively high level as compared with the pressure in chamber 46. Chamber 42 is still, of course, exposed to the accumulator passage 236 which has its inlet end at position I and its discharge end at the trailing side of the apex seal blade 124 at position III. The accumulator passage 238 is still exposed to the intake chamber 46 at its end at position I through passages 234 and is exposed to the exhaust chamber 44 at its end at position II (FIG. 33).

With reference to FIG. 33, in position II, the high pressure from the expansion chamber 42 is exposed through passage 234 to the inlet end of the accumulator passage 240. The relatively high pressure from the expansion chamber 42, although reduced, acts in the same manner on the seal blade 124 in position II as previously described in connection with the seal blade 124

at position II in connection with FIG. 29 in the firing position of the rotor.

The apex seal blade 124 in position III (FIG. 34) is exposed to the pressure at the discharge ends of passages 236 and 240 on its trailing and leading sides, respectively, as previously described in connection with FIG. 30 in the firing position of the rotor. Again, however, there is a substantial drop in the pressure between the inlet ends of passages 236 and 240 at positions I and II, respectively, and their discharge ends at position III reducing pressure at 24 on the seal blade working tip. There is a further pressure drop between the discharge ends of the passages 236 and 240 and chambers 44 and 46, respectively, due to the size of the passage 234, the space between the leading side surface of the blade 124 in position III and the leading side wall of the groove 134, and the reed valve action of the seal blade 124 between the leading and trailing side walls of the groove 134.

FIG. 35 illustrates the rotor at the end of a power stroke wherein the apex seal blade 124 at position I is moving past the lobe 28. Compression has begun in chamber 46 since the apex seal blade 124 at position III has moved past the intake port 23 and the substantially maximum expansion of chamber 42 has occurred just prior to the seal blade 124 at position II moving past the exhaust port 34.

As shown in FIG. 36, the accumulator passage 236 is exposed to the pressure in chamber 42, which is substantially reduced from the position of FIG. 31, and the accumulator passage 238 on the trailing side of the seal blade in position I is exposed to chamber 46 through passage 234. In position II (FIG. 37), the accumulator passage 238 has its inlet end exposed to the exhaust chamber 44 on the leading side of the seal blade 124 and the inlet end of the accumulator passage 240 is exposed to the expansion chamber 42 through the passage 234.

With reference to FIG. 38, the discharge ends of passages 236 and 240 are exposed to chambers 44 and 46, respectively, as previously described in connection with FIG. 34. Again, however, there is a substantial pressure drop between the inlet and discharge ends of the accumulator passages 236 and 240. Moreover, the pressure differential between the expansion chamber 42 and compression chamber 46 in the position of the rotor shown in FIG. 35 is substantially reduced from the condition illustrated in FIG. 31. Consequently, the pressure differential between the inlet and discharge ends of the accumulator passage 240 due to the reduced pressure differential between chambers 42 and 46 is substantially reduced (and thus the pressure on the seal blade tips at 24) in the position shown at FIG. 35.

In FIG. 39, the rotor has moved from the position of FIG. 35 and the apex seal assembly at position II has moved past the exhaust port 24 and an intake phase is beginning at chamber 46 defined between the apex seals at positions II and III. The chamber 42 defined between the apex seals at positions I and III is at near peak compression just prior to moving into the ignition position.

As shown in FIG. 40, the accumulator passage 238 is exposed to chamber 42 through the passages 234, and the accumulator passage 236 is exposed to the chamber 44 through the space between the leading surface of

the seal blade and the leading side wall of the groove 134.

In FIG. 41, the seal assembly at position II is located between the intake and exhaust chambers. The discharge end of the accumulator passage 238 is exposed to the intake chamber, and the discharge end of the accumulator passage 240 is exposed to the exhaust chamber. The apex seal blade 124 at position II in FIG. 41 may act in the manner of a reed valve in leading the pressure from the discharge ends of passage 238 and 240 into the respective intake and exhaust chambers 46 and 44.

The apex seal assembly 124 at position III has its leading side exposed to the compression chamber 42 which is in a relatively high pressure condition as compared with the pressure conditions in intake chamber 46 on the left-hand side of the seal blade 124 in FIG. 2. The accumulator passage 236 is exposed to the intake chamber through passage 234, and the accumulator passage 240 has its inlet end exposed to the compression chamber 42.

In all positions of the rotor, the leading side of each seal blade 124 is spaced from the leading side wall of the groove 134 to permit communication between the ends of the respective accumulator passages 236, 238, and 240 on the lead sides at positions I, II, and III, respectively, while the trailing side surfaces of the seal blade are always closed against the trailing side wall of the respective groove 134. The diameters of the accumulator passages 236, 238, and 240 may be chosen to control the pressure drop between the ends thereof. Similarly, the diameter and number of passages 234 in the seal blades 124 can be chosen so as to produce the controlled pressure condition acting on the seal blades, particularly the seal blades in the left-hand and right-hand firing positions at ignition and explosion of the gases.

While the invention has been illustrated and described in several specific forms, it will be understood by those skilled in the art that the invention is not limited to the exact construction shown. To the contrary, various alterations in the construction and arrangement of parts, all falling within the scope and spirit of the invention, will be apparent to those skilled in the art.

The embodiments of the invention in which an exclusive property or privilege is claimed are defined as follows: extend from the groove.

1. A coupling seal member for a rotary engine or the like comprising: a cylindrical body; a groove formed in said body and extending along the length thereof; and a seal blade pressure member formed on said coupling seal member adapted to engage a seal blade at least partially received in said groove, said body having an outer end with an upper contacting surface for sliding sealing engagement with a surface of another member, and a lower relieved surface inclined away from said contacting surface.

2. A coupling seal member as claimed in claim 11 wherein said coupling seal member is formed with an extension arm projecting from said cylindrical body on one side of said groove, said seal blade pressure member being formed on said extension arm and being adapted to engage a coupling seal cam surface formed on an apex seal blade received in said groove.

3. A seal blade for a rotary engine or the like adapted for use in a groove of a coupling seal member comprising: a tip portion with a working surface defined

thereon, said tip portion having a leading and a trailing edge, a trailing side surface extending from the trailing edge of said tip portion, a leading side surface extending from the leading edge of said tip portion, and a cam surface formed on said trailing side surface, said cam surface comprising a concave surface formed on said trailing side surface, further comprising a pair of coupling seal cam surfaces formed on the leading side surface of said seal blade, the outer ends of said seal blade each having upper and lower surfaces, the lower surfaces being relieved inwardly with respect to the upper surfaces.

4. A seal blade as claimed in claim 3 wherein the working surface of said outer tip portion has a leading portion and a trailing portion and an imaginary rake angle line intersects said tip portion such that the leading portion of said working surface is on one side of said rake angle line and the trailing portion of said working surface is on the other side of said rake angle line, said leading portion having a curvature the radius of which has a center located substantially on said rake angle line, said trailing portion having a curvature the radius of which has a center located on the leading side of said rake angle line, the radius of curvature of said trailing portion being larger than the radius of curvature of said leading portion such that the trailing portion of the working surface extends further from said rake angle line than the leading portion of said working surface.

5. A seal blade as claimed in claim 4 wherein said rake angle intersects the bottom surface of said seal blade at a location closer to said trailing side surface than the said leading side surface.

6. A rotor for a rotary engine or the like of the type having a housing forming working chambers with a rotor rotatable in the housing and having apex portions with grooves and apex seals received therein for engaging the wall of the housing to form the working chambers and wherein the seal blades are loosely received in the grooves to allow leakage into the grooves from the working chambers, said rotor comprising: a plurality of apex portions; a groove formed in each of said apex portions extending substantially parallel to the axis of rotation of said rotor; a plurality of accumulator passages formed in said rotor, the number of said accumulator passages corresponding to the number of said grooves; each of said accumulator passages having one end communicating with the leading side wall of the groove of one apex portion and its other end communicating with the trailing side wall of the apex portion adjacent to and trailing said one apex portion.

7. A seal blade for a rotary engine or the like comprising: a tip portion with a working surface defined thereon, said tip portion having a leading and a trailing edge; a trailing side surface extending from the trailing edge of said tip portion; a leading side surface extending from the leading edge of said tip portion; said trailing side surface being formed with an upper concave cam surface and a lower convex portion; said leading side surface being concave substantially throughout its length; and outer ends extending between said leading and trailing side surfaces, said outer ends each having an upper surface adjacent the respective tip portions, and a lower surface depending from said upper surface and relieved with respect to said upper surface.

8. A sealing assembly for providing a sliding seal between two members, one of which members is movable

relative to the other, said sealing assembly comprising: a groove formed in said one member, said groove extending substantially transversely of the direction of movement of said member relative to the other member, said groove having a leading side wall, a trailing side wall, and a bottom wall extending between said side walls; a seal blade received in said groove, said blade having a tip portion projecting from said groove with a working surface defined thereon for sliding, sealing engagement with a surface of said other member, said blade having a trailing side surface extending from the trailing edge of the outer tip portion and disposed in opposed relationship to said trailing side wall of said groove; said blade having a leading side surface extending from the leading edge of said outer tip portion and disposed in opposed relationship to said leading side wall of said groove; said trailing side wall of said groove being formed with a convex ramp portion adjacent the open end of said groove, and said trailing side surface of said blade being formed with an upper concave portion having a radius of curvature larger than the radius of curvature of said convex ramp portion such that forces urging the surface of said concave portion into contact with said convex ramp portion produce reaction force components between said concave and convex portions that urge said blade to extend from said groove.

9. A sealing assembly for providing a sliding seal between two members, one of which members is movable relative to the other, said sealing assembly comprising: a groove formed in said one member, said groove extending substantially transversely of the direction of movement of said member relative to the other member, said groove having a leading side wall, a trailing side wall, and a bottom wall extending between said side walls; a seal blade received in said groove, said blade having a tip portion projecting from said groove with a working surface defined thereon for sliding, sealing engagement with a surface of said other member, said blade having a trailing side surface extending from the trailing edge of the outer tip portion and disposed in opposed relationship to said trailing side wall of said groove; said blade having a leading side surface extending from the leading edge of said outer tip portion and disposed in opposed relationship to said leading side wall of said groove; cooperating convex and concave cam surfaces on said trailing side wall of said groove and trailing side surface of said blade, respectively, operable in response to forces urging said trailing side surface into contact with said trailing side wall to produce reaction force components urging said blade to extend having upper and lower surfaces, the lower surfaces being relieved inwardly with respect to the upper surfaces.

10. A sealing assembly for providing a sliding seal between two members, one of which members is movable relative to the other, said sealing assembly comprising: a groove formed in said one member, said groove extending substantially transversely of the direction of movement of said member relative to the other member, said groove having a leading side wall, a trailing side wall, and a bottom wall extending between said side walls; a seal blade received in said groove, said blade having a tip portion projecting from said groove with a working surface defined thereon for sliding, sealing engagement with a surface of said other member, said blade having a trailing side surface extending from

the trailing edge of the outer tip portion and disposed in opposed relationship to said trailing side wall of said groove; said blade having a leading side surface extending from the leading edge of said outer tip portion and disposed in opposed relationship to said leading side wall of said groove; cooperating cam surfaces on said trailing side wall of said groove and trailing side surface of said blade operable in response to forces urging said trailing side surface into contact with said trailing side wall to produce reaction force components urging said blade to extend from said groove, said cam surfaces comprising a convex surface on said trailing side wall and a concave surface on said trailing side surface, said concave surface having a larger radius of curvature than said convex surface such that there is a substantial line contact engagement between the trailing side wall and trailing side surface, further including a pair of cylindrical coupling seal recesses formed in said one member at opposite ends of said groove, a coupling seal member received in each said recesses, said coupling seal members each having a cylindrical body rotatable in the respective coupling seal recess, a groove formed in said body and disposed coextensively with the groove in said one member and receiving an end portion of said seal blade, and means interengageable between each of said coupling seal members and said seal blade operable to urge said coupling seal members to project axially from the respective coupling seal recesses and to simultaneously urge said apex seal blade toward a centered position in said groove and to extend from said groove.

11. A sealing assembly for providing a sliding seal between two members, one of which members is movable relative to the other, said sealing assembly comprising: a groove formed in said one member, said groove extending substantially transversely of the direction of movement of said member relative to the other member, said groove having a leading side wall, a trailing side wall, and a bottom wall extending between said side walls; a seal blade received in said groove, said blade having a tip portion projecting from said groove with a working surface defined thereon for sliding, sealing engagement with a surface of said other member, said blade having a trailing side surface extending from the trailing edge of the outer tip portion and disposed in opposed relationship to said trailing side wall of said groove; said blade having a leading side surface extending from the leading edge of said outer tip portion and disposed in opposed relationship to said leading side wall of said groove; cooperating cam surfaces on said trailing side wall of said groove and trailing side surface of said blade operable in response to forces urging said trailing side surface into contact with said trailing side wall to produce reaction force components urging said blade to extend from said groove, said cam surfaces comprising a convex surface on one of said trailing side wall and trailing side surface, and a convex surface on the other of said trailing side wall and trailing side surface, said convex surface being formed on said trailing side wall and said concave surface being formed on said trailing side surface, said concave surface having a larger radius of curvature than said convex surface such that there is a substantial line contact engagement between the trailing side wall and trailing side surface, further including a pair of cylindrical coupling seal recesses formed in said one member at opposite ends of said groove, a coupling seal member received in

each of said recesses, said coupling seal members each having a cylindrical body rotatable in the respective coupling seal recess, a groove formed in said body and disposed coextensively with the groove in said one member and receiving an end portion of said seal blade, and means interengageable between each of said coupling seal members and said blade operable to urge said coupling seal members to project axially from the respective coupling seal recesses and to simultaneously urge said apex seal blade toward a centered position in said groove and to extend from said groove.

12. An assembly as claimed in claim 11 wherein said last named means comprises a pair of coupling seal cam surfaces formed on said seal blade, and a seal blade pressure member formed on each of said coupling seal members, said seal blade pressure members each being engageable with one of said cam surfaces in response to rotation of the respective coupling seal members in their respective recesses.

13. An assembly as claimed in claim 12 wherein each of said coupling seal members has an outer end with an upper contacting surface for sliding sealing engagement with a surface spaced from each of the respective ends of said one member, and a lower relieved surface inclined away from said contacting surface toward the respective recess.

14. An assembly as claimed in claim 13 wherein said coupling seal cam surfaces are formed on the leading side surface of said seal blade, and wherein said coupling seal members are each formed with an extension arm projecting from said cylindrical body along the leading side surface of said seal blade, said seal blade pressure member being formed on said extension arm and engageable with one of said coupling seal cam surfaces.

15. An assembly as claimed in claim 14 wherein the outer ends of said seal blade each has upper and lower surfaces, the lower surfaces being relieved inwardly with respect to the upper surfaces.

16. An assembly as claimed in claim 15 wherein said one member comprises a rotor for a rotary engine or the like.

17. An assembly as claimed in claim 16 wherein said rotor has at least one apex portion, and wherein said groove is formed in said apex portion.

18. A sealing assembly for providing a sliding seal between two members, one of which members is movable relative to the other, said sealing assembly comprising: a groove formed in said one member, said groove extending substantially transversely of the direction of movement of said member relative to the other member, said groove having a leading side wall, a trailing side wall, and a bottom wall extending between said side walls; a seal blade received in said groove, said blade having a tip portion projecting from said groove with a working surface defined thereon for sliding, sealing engagement with a surface of said other member, said blade having a trailing side surface extending from the trailing edge of the outer tip portion and disposed in opposed relationship to said trailing side wall of said groove; said blade having a leading side surface extending from the leading edge of said outer tip portion and disposed in opposed relationship to said leading side wall of said groove; cooperating cam surfaces on said trailing side wall of said groove and trailing side surface of said blade operable in response to forces urging said trailing side surface into contact with said trailing side

wall to produce reaction force components urging said blade to extend from said groove, further including at least one cylindrical coupling seal recess formed in said one member at one end of said groove, a coupling seal member received in said recess, said coupling seal member having a cylindrical body rotatable within said recess, said body having a groove formed therein and disposed coextensively with the groove in said one member and receiving an end portion of said seal blade, further including means engageable between said coupling seal member and said seal blade operable to urge said coupling seal member to project axially from said coupling seal recess and to simultaneously urge said seal blade toward a centered position in said groove and to extend from said groove.

19. An assembly as claimed in claim 18 wherein said last named means comprises a coupling seal cam surface on said seal blade, and a seal blade contact member on said coupling seal member, said seal blade contact member being engageable with said coupling seal cam surface in response to rotation of said coupling seal member with respect to said recess.

20. An assembly as claimed in claim 19 wherein said coupling seal member is otherwise out of contact with said seal blade when said seal blade contact member is engaged with said coupling seal recess.

21. An assembly as claimed in claim 20 wherein said seal blade contact member is formed on the leading side wall of the groove in said coupling seal member, and said coupling seal cam surface is formed on the leading side surface of said seal blade.

22. An assembly as claimed in claim 20 wherein said coupling seal member is formed with an extension arm projecting from said cylindrical body along the leading side surface of said seal blade, said seal blade contact member being formed on said extension arm, and said coupling seal cam surface being formed on the leading side surface of said seal blade.

23. An assembly as claimed in claim 22 wherein said coupling seal cam surfaces are formed on the leading side surface of said seal blade, and wherein said coupling seal members are each formed with an extension arm projecting from said cylindrical body along the leading side surface of said seal blade, said seal blade pressure member being formed on said extension arm and engageable with one of said coupling seal cam surfaces.

24. An assembly as claimed in claim 23 wherein said coupling seal member has an outer end with an upper contacting surface extending to the end of said extension arm for sliding engagement with a surface spaced from the associated end of said one member, and a lower relieved surface inclined away from said contacting surface toward the respective recess.

25. An assembly as claimed in claim 24 wherein the leading side wall of the groove in said one member is convex and the leading side surface of said seal blade is concave.

26. An assembly as claimed in claim 25 wherein said seal blade contact member engages said coupling seal cam surface at a point spaced from the substantial line contact between said trailing side surface and trailing side wall on the opposite side thereof from said bottom wall of said groove of said one member to thereby urge the edge of the leading side surface of said seal blade adjacent said bottom wall to engage said leading side

wall of said groove in said one member with a substantial line contact.

27. An assembly as claimed in claim 26 wherein said cam surfaces comprise a convex surface on one of said trailing side wall and trailing side surface, and a concave surface on the other of said trailing side wall and trailing side surface.

28. An assembly as claimed in claim 27 wherein said convex surface is formed on said trailing side wall and said concave surface is formed on said trailing side surface.

29. An assembly as claimed in claim 28 wherein said concave surface has a larger radius of curvature than said convex surface such that there is a substantial line contact engagement between the trailing side wall and trailing side surface.

30. An assembly as claimed in claim 29 wherein said convex surface extends from the outer edge of said groove opposite the bottom wall thereof, and said concave surface extends from the trailing edge of said tip portion, and wherein said trailing side wall has a concave lower portion extending from said convex surface toward said bottom wall, and said trailing side surface has a lower convex portion extending from the lower edge of said concave surface.

31. An assembly as claimed in claim 30 wherein the working surface of said outer tip portion has a leading portion and a trailing portion and an imaginary rake angle line intersects said tip portion such that the leading portion of said working surface is on one side of said rake angle line and the trailing portion of said working surface is on the other side of said rake angle line, said leading portion having a curvature the radius of which has a center located substantially on said rake angle line, said trailing portion having a curvature the radius of which has a center located on the leading side of said rake angle line, the radius of curvature of said trailing portion being larger than the radius of curvature of said leading portion such that the trailing portion of the working surface extends further from said rake angle line than the leading portion of said working surface.

32. An assembly as claimed in claim 31 wherein said rake angle line intersects the bottom surface of said seal blade at a location closer to said trailing side surface than to said leading side surface, and wherein said rake angle line intersects the bottom wall of the groove in said one member at a location closer to said trailing side wall than to said leading side wall.

33. An assembly as claimed in claim 32 further including at least one passage extending through said seal blade having an opening in the tip portion on the trailing side of the trailing portion of the working surface thereof.

34. An assembly as claimed in claim 33 further including a seal blade spring received in the groove of said one member and biasing said seal blade outwardly with respect to said groove.

5 35. An assembly as claimed in claim 34 further including a coupling seal spring received in said coupling seal recess and biasing said coupling seal member to extend outwardly from said recess.

10 36. An assembly as claimed in claim 35 wherein said seal blade spring has a central portion that rests on the bottom wall of said groove and a pair of spring arms extending upwardly and outwardly in opposite directions from said central portion, and further including a pair of projections on opposite ends of said blade depending 15 below the bottom surface thereof, the junctions between said bottom surface and said projections being curved, and said spring arms being engaged with the respective junctions and having a curvature conforming substantially to said junctions.

20 37. An assembly as claimed in claim 33 wherein said one member comprises a seal blade retaining member.

38. An assembly as claimed in claim 37 including a rotor for a rotary engine or the like, said retaining member being mounted on said rotor.

25 39. An assembly as claimed in claim 38 wherein said rotor has at least one apex portion defined by said retaining member.

30 40. An assembly as claimed in claim 39 further including at least one pair of oppositely extending side seal slots formed in said one end of said retaining member.

35 41. An assembly as claimed in claim 40 wherein said rotor has an end face lying in substantially coplanar relationship with said one end of said retaining member, at least one pair of side seal strips mounted within said end face, one end of each of said side seal strips being received in a respective one of said side seal slots.

40 42. An assembly as claimed in claim 41 wherein a clearance is maintained between the ends of said side seal strips and the walls of the respective side seal notches in said retaining member.

45 43. An assembly as claimed in claim 42 further including a pair of oppositely extending side seal slots in said coupling seal member, each of said coupling seal side seal slots being positioned in alignment with a respective one of said side seal strips in said retaining member to form an extension thereof, the respective ends of said side seal strips being received in the slots in said coupling seal members, and wherein a clearance 50 is always maintained between the ends of said side seal strips and the surfaces of the respective side seal slots in said coupling seal members in all positions of said coupling seal member.
